SWITCH AND SIGNAL CONTROL SYSTEM
FOR RAILROADSNelson B. Coley, Rochester, N. Y., assignor to
General Railway Signal Company, Rochester,
N. Y.

Application May 8, 1939, Serial No. 272,319

30 Claims. (Cl. 246—134)

This invention relates to switch and signal control systems for railroads, and it more particularly pertains to such systems of the entrance-exit type which are characterized by the establishment of each route in the track layout in response to the designation by an operator of the opposite ends of that route.

For designation of the route ends, push buttons, or other suitable contactors, are provided on a control panel in a tower or control office within convenient reach of an operator. In order that an operator can readily associate each button with the particular route end for which it is provided, and for the purpose of facilitating the dispatching of trains through the track layout, a miniature track diagram is provided on the control panel representative of the track layout in the field for which the system is provided, and the buttons are distributed along the track diagram at points representative of the signal locations which define the route ends with which those buttons are respectively associated. Indication means, such as indicator lamps, are usually provided along the miniature track diagram in order that an operator may be informed as to the routes established, the indications of the signals, and the condition of occupancy of the various track sections.

The usual manipulation by an operator in designating a route to be set up is to first designate the route end that is to be the entrance point in the route being set up, and to then designate the route end that is to be the exit point for that route. The sequence of operation of the buttons for the respective ends of each route can be used as a means for determining the direction for which the signals shall be cleared, or the direction can be determined by providing a button on the control panel for the entrance point at each signal location and a button on the control panel for the exit point at each signal location, thus requiring an operator to define the direction for which the signals are to be cleared by the kind of button he actuates, namely, an entrance or an exit button.

An object of the present invention is to provide, by means of two circuit networks, a route selecting system by which normal and reverse switch control relays controlled by such networks select the desired position for each track switch included in each available route having its entrance and exit ends designated by an operator, irrespective of the number of track switches included between the route ends designated.

Another object of the present invention is to so

select the control of the normal and reverse switch control relays that either a normal or a reverse switch control relay is picked up for each trailing track switch included in an available route emanating from a designated entrance point. When optional routes are involved and a track switch can be trailed either normal in one route or reverse in another route emanating from a designated entrance point, the normal position of that track switch is generally selected by the picking up of its normal switch control relay in preference to its reverse switch control relay. When the circuits provide such preference, and optional routes are involved, preference is given to the available route diverging nearest the designated entrance point, except when such diverging route is an inferior run-around route. Where inferior run-around routes are involved, the most direct route is given preference by the system because of the normal switch control relays having preference over the reverse switch control relays.

Another object of the present invention is to provide a means whereby a particular route can be given preference over other optional routes between designated entrance and exit points, even if that route does not diverge via the crossover nearest the designated entrance point. Such preference is often required in practice in order to prevent the unnecessary tying up of routes, or in order to cause a high speed track switch common to several routes to be used when available in preference to lower speed track switches. To provide such mode of operation the reverse switch control relay is given preference over the normal switch control relay, responsive to the designation of an entrance point, for the particular track switch that can select the desired preferred route if operated to a reverse position.

Another object of the present invention is to select the control of the normal and reverse switch control relays in the circuit networks in such a manner that either a normal or a reverse switch control relay is picked up for each track switch trailed from each designated exit point when a route is definitely selected up to that track switch from the exit point designated. Such control of the switch control relays responsive to the designation of each exit point is accomplished by use of the same circuit networks that are used for energizing the normal and reverse switch control relays responsive to the designation of an entrance point. Thus, the same circuits that are used in picking up normal and reverse relays for track switches trailed from each entrance point are used in picking up those normal and reverse

relays when those track switches are trialed from each exit point for the corresponding route end.

Another object of the present invention is to cause the operation of the track switches only when such operation is required in setting up the route actually selected by the normal and reverse switch control relays after an exit point has been designated. That is, the picking up of normal and reverse switch control relays responsive to the designation of an entrance point for track switches that are not actually included in the route which is completely selected after designation of the exit point, is ineffective to cause the positioning of the track switches with which those normal and reverse switch control relays are associated. Such mode of operation is accomplished because the circuits provide that a track switch can be positioned, responsive to route end designation by an operator, only after a switch control relay has been picked up for that track switch dependent upon designation of an entrance point, and another switch control relay for that track switch has been picked up dependent upon the designation of the exit point for that route. Thus, because the nature of the system is such that switch control relays are picked up responsive to the designation of the exit point, only to correspond with the route to be selected, the track switches are positioned only when they are included in the route actually selected.

Another object with respect to the execution of the switch controls in accordance with the route selected is to provide a difference in starting time of the switch machine motors for the track switches included in each route selected in order to better distribute the power load. Such difference in starting time is provided by the cascade manner in which the switch control relays are picked up responsive to the designation of the exit point. That is, responsive to the designation of an exit point in setting up a route, the switch control relays are picked up in succession, one relay or one small group of relays at a time, starting with the relays for the track switch nearest the exit point designated; and, because the picking up of each of those relays causes the operation of the switch machine for that track switch, the motors are started successively, one motor or one small group of motors at a time, starting with the motor for the track switch nearest the designated exit point.

Having thus pointed out in a general manner some of the objects of the present invention, due to the complexity of the system, it is believed that other objects, purposes and characteristic features of the present invention will be more thoroughly understood from reference to the accompanying drawings and as they are pointed out hereinafter in the description of the present invention.

In describing the invention in detail, reference will be made to the accompanying drawings, in which like reference characters designate corresponding parts throughout the several illustrations, in which similar letter reference characters are used to designate parts of a similar general nature, such parts being generally made distinctive by reason of preceding numerals or by preceding letter reference characters representative of the signal locations, and in which:

Figs. 1A and 1B, when placed end-to-end, illustrate the two self-selecting circuit networks provided for energizing the normal and reverse switch control relays for the track layout shown in Fig. 3;

Fig. 2 illustrates various switch and signal control circuits for a particular crossover as typical of the circuits provided for each of the crossovers included in the track layout for which the system is provided;

Fig. 3 illustrates the track layout for which the circuit networks illustrated in Figs. 1A and 1B are provided, together with the signal control circuits relative to the control of the signals associated with that particular track layout;

Fig. 4, when placed end-to-end with Fig. 1A, illustrates how the circuit networks can be provided to give preference to a particular given one of a plurality of optional routes; and

Figs. 5A and 5B, when placed side by side, illustrate a means of providing indications on the section of the track diagram illustrated in Figs. 1A and 1B.

Fig. 6 illustrates the switch control for a particular single switch as typical of the circuits provided for each of the single track switches that may be included in any track layout for which the system is provided.

For the purpose of facilitating in the description of the present invention, reference is made from time to time to functions common to all parts of a similar kind or class by use of the letter reference characters common to such parts without their distinctive preceding letters or numerals. Such a reference is to be understood to apply to any parts designated in the drawings by letter reference characters that are similar except for preceding numerals, or preceding letter reference characters characteristic of the various signal locations.

In order to simplify as much as possible, the disclosure of the present invention, various diagrammatic and conventional illustrations have been employed in the drawings for the purpose of facilitating the disclosure of the present invention as to the principles involved and the mode of operation, rather than for showing the specific construction and arrangement of parts that would be employed in practice. Thus, the various relays and their contacts are shown in a conventional manner, certain circuit details well known to those familiar with the art are merely indicated by dotted lines, and symbols are used to indicate the connections to the terminals of batteries or other sources of electric current instead of showing all of the wiring connections to such terminals.

The symbols (+) and (-) are employed to indicate the positive and negative terminals respectively of suitable batteries or other sources of direct current, and the circuits with which those symbols are used always have current flowing in the same direction. If alternating current is used instead of direct current, the symbols are to be considered as representative of the instantaneous relative polarities.

Track layout.—With reference to Fig. 3, the track layout for this particular embodiment of the present invention is illustrated in which two parallel tracks are connected by crossovers having the track switches 2TSA, 2TSB, 4TSA and 4TSB, and the lower one of the two parallel tracks is illustrated as being connected to a third track by the track switch 3TS.

Each of the track switches is positioned by a power operated switch machine SM of a suitable type, such, for example, as the switch machine shown in the patent to W. K. Howe, Patent No. 1,466,903, dated September 4, 1923. The switch machine motors are assumed to have a suitable means of control to provide the features generally

required in practice with respect to their control, such as over-load protection, such, for example, as is shown in the patent to W. H. Hoppe et al., Patent No. 1,877,876, dated September 20, 1932.

Inasmuch as the track switches for each end of a crossover are generally positioned in correspondence with each other, for the purpose of simplifying the present disclosure, only one switch machine has been shown for the positioning of the track switches for both ends of each crossover, however, it is to be understood that a separate switch machine can be provided for each end of each crossover in accordance with the requirements of practice. Thus, switch machine 2SM is provided for positioning track switches 2TSA and 2TSB, switch machine 3SM is provided for positioning track switch 3TS and switch machine 4SM is provided for positioning track switches 4TSA and 4TSB.

The locked position of each of the track switches in correspondence with the lock position of the corresponding switch machine is repeated in the usual manner by a polar neutral relay WP. Each of the relays WP is assumed to be energized with its polar contacts operated to a right hand position when the track switches with which it is associated are in correspondence with the normal locked position of the switch machine SM, and each relay WP is energized with its polar contacts operated to a left hand position when the associated track switches and switch machine are both in a reverse locked position. Whenever the switch points and/or the switch machine are unlocked the relay WP associated therewith is deenergized.

For the purpose of selecting such control for each of the relays WP, point detector contact mechanisms are provided of the type shown, for example, in the patent to C. S. Bushnell, Patent No. 1,517,236, dated November 25, 1924.

Signals are provided for governing traffic through the track layout in both directions, signals A and B having been provided for governing east bound traffic to the right through the track layout illustrated in Fig. 3, and signals C, D and E having been provided for governing west bound traffic to the left through that track layout.

The signals have been illustrated as being of the color light type having individual color lamp units, the upper lamp unit providing a green clear indication, and the lower lamp unit providing a red danger indication. It is to be understood that additional indications, such, for example, as a yellow indication for caution can be provided in accordance with the requirements of practice, and that other types of signals such as search light and semaphore signals can be used.

The track layout illustrated in Fig. 3, is shown as having been divided into track sections by the usual insulated joints, and it is to be understood that the usual type of track circuits are provided for each of the sections. Track sections 7T, 8T, 9T and 10T have been illustrated as having been provided for the control of track relays 7TR, 8TR, 9TR and 10TR respectively. It is to be understood that the track switches are properly bonded to provide the usual fouling protection.

Control machine.—A principal part of the control machine for governing traffic through the track layout is a control panel within convenient reach of an operator upon which is constructed a miniature track diagram of the track layout for which the system is provided. Thus, for this embodiment of the present invention, the track

diagram illustrated at the top of Figs. 1A and 1B is illustrative of the track layout shown in Fig. 3. Suitable indicator lamps are provided along the miniature track diagram in order that an operator

5 can be well informed as to the condition of occupancy of the track sections, the indications displayed by the various signals, and the routes which are established through the interlocking plant. The lamps (see Figs. 5A and 5B) 10 are assumed to be mounted on the back of the panel behind translucent strips of which the track diagram is constructed. For the purpose of limiting the light from each of the lamps to the particular portion of the track diagram with 15 which that lamp is associated, suitable baffles 216, or the like, are provided at the limits of each of the portions associated with each of the lamps.

A control button NB (see Figs. 1A and 1B) is 20 provided on the miniature track diagram at a point representative of the entrance point to each route, and a control button XB is provided on the miniature track diagram at a point representative of the exit point to each route. Thus, because traffic is provided in both directions in the present embodiment of the invention through the track layout, each of the route ends has associated therewith an entrance button NB and an exit button XB. Inasmuch as the route ends are 25 determined by the location of the signals, the buttons ANB and AXB (see Fig. 1A) are provided on the miniature track diagram at a relative position to the signal A for the corresponding route end at the track layout. Thus, in a similar 30 manner, an entrance button NB and an exit button XB is provided for each of the signal locations.

Each of the entrance buttons NB is of the 35 push-pull type, and is biased to a center position from which it can either be depressed or pulled out. Each button NB is provided with a normally closed contact which is maintained closed when the button is depressed, and another contact which is closed only when the button is 40 in a depressed position. The construction of the button to provide such a contact arrangement can be provided in a manner shown, for example, in the prior application of J. F. Merkel, Ser. No. 158,720, filed August 12, 1937. Each of the exit 45 buttons XB is of the self-restoring push-button type having a contact closed only when the button is depressed.

Although separate buttons have been shown in 50 this embodiment of the invention for designation of entrance and exit points, it is to be understood that a single button could as well be employed for each of the route ends, having distinctive positions for designation of entrance and exit points for that route end. It is also to be 55 understood that a single push button could as well be employed for designation of both entrance and exit points if means is provided, such as by sequence of operation of the buttons, for designation of entrance and exit points, for determining the direction in setting up routes, such as is shown, for example, in the prior application of N. D. Preston, Ser. No. 183,499, filed January 5, 1938.

An auxiliary switch control lever SML is provided for each of the crossovers and for each single track switch in order that an operator may have individual control of each crossover and each single track switch for use in setting up routes not provided by the self-selecting network, and for use in freeing the track switches from

obstructions, such, for example, as snow and ice.

System devices.—Each of the entrance points in the track layout has therewith in the control office an entrance relay NR which is energized responsive to the designation of that particular entrance point by an operator, and which is maintained energized dependent for de-energization upon the passage of a train past that entrance point, or dependent for de-energization upon manual actuation of the entrance button NB for that particular entrance point to a distinctive position from that used for designation of such entrance point in designating a route to be set up.

An exit relay XR is provided for the exit point for each signal location, and each of such exit relays is responsive to the designation of an exit point in setting up a route by the depression of the exit button XB for that particular route end. Each exit relay XR can be picked up responsive to the designation of an exit point in setting up a route only if a route is available between that exit point and the entrance point designated for that route. When once picked up each exit relay XR is maintained energized dependent upon the picked up condition of the entrance relay NR for the entrance point to the corresponding route.

Relays AN, BN, N, AR, BR and R are normal and reverse switch control relays energized in the circuit networks responsive to the picking up of the entrance and exit relays NR and XR respectively. Relays AN, BN and N are provided for causing operation of their respective track switches to normal positions, and relays AR, BR and R are provided for causing the operation of their respective track switches to reverse positions. The relays AN and AR for each crossover are associated with the track switches at the upper end of their respective crossovers and the relays BN and BR for each crossover are associated with the track switches at the lower end of their respective crossovers. That is, for example (see Fig. 2), the relays 2AN and 2AR are associated with track switch 2TSA, and the relays 2BN and 2BR are associated with track switch 2TSB. The positioning of the track switch for either end of each crossover is, however, dependent upon the picking up of the AN or AR relay, as the case may be, for one end of the crossover and the BN or BR relay for the corresponding position for the opposite end of the crossover.

Relays N and R are provided for causing the operation of their respective single track switch to a respective normal or reverse position, such positioning of the track switch being effective only when an execution relay X associated with that single track switch is picked up.

With reference to Fig. 2, two lock relays L are provided for each crossover; one for the detector track section at each end of the crossover, for allowing the operation of the track switches for that crossover only at times when such operation is safe and desirable. It is believed that it will be readily apparent that only one lock relay is required for each single track switch, and it is also to be understood that, when one detector track section is common to a number of track switches, only one lock relay L associated with that detector track section will be required for the group of track switches, dependent upon the requirements of practice. That is, one lock relay L can be provided per track circuit, or one lock relay L can be provided per single track

switch and two lock relays per crossover. For this embodiment of the present invention one lock relay L is provided per single track switch and two lock relays L are provided per crossover.

5 A polar neutral relay WZ is provided for each of the crossovers and each single track switch in accordance with the circuits shown as typical in Fig. 2. Each relay WZ is responsive to the normal and reverse switch control relays, and 10 when energized causes the operation of the switch machine for the associated track switch. Each of the relays WZ provides a means by which each track switch will complete its operation when such operation has been initiated, irrespective of 15 the restoration to normal of the normal and reverse switch control relays, and it also provides a means by which reversal of a switch machine in midstroke can be effected, as is sometimes required when obstructions prevent a completion 20 of the operation to the desired position.

For repeating the locked position of the track switches in correspondence with the switch controls selected, normal and reverse correspondence relays NCR and RCR respectively are provided.

25 With reference to Fig. 3, a signal control relay G is provided for governing the indication displayed by each signal. When a signal control relay G is in a dropped away position, the corresponding signal displays a red danger indication, 30 and when a signal relay G is picked up, the corresponding signal displays a green clear indication.

Having thus considered the general organization of the apparatus in accordance with the 35 present invention, consideration will now be given more particularly to the mode of operation of the system and the principles involved.

Operation

40 *Normal conditions.*—The normal conditions of the system are assumed to be those conditions that exist when the indicator lamps are all extinguished to indicate that there are no routes set up, or partially set up, no track sections occupied within the interlocking plant, and the signals governing traffic through the track layout are all at danger. The track switches, under normal conditions, are in the positions required in the route in which they were last included. Thus, 45 under the conditions assumed as normal in the present disclosure, the track switches are assumed to be in the normal positions last required for through routes on the two parallel tracks.

Under normal conditions the relays are all de-55 energized as illustrated in the accompanying drawings except the track relays TR (see Fig. 2), the switch repeater relays WP, the lock relays L, and the route locking relays ES and WS. The track relays TR and the switch repeater relays 60 WP are normally energized by circuits well known to those familiar with the art, and the lock relays for each track switch are energized in accordance with the typical circuits shown in Fig. 2 for the lock relays 7L and 8L associated with the track switches 2TSA and 2TSB. Relay 7L is normally maintained energized by a circuit closed from (+), through a circuit including front contact 20 of relay 7WS, front contact 21 of relay 7TR, front contact 22 of relay 7ES, winding of relay 7L, and front contact 23 of relay 7L, to (-). Relay 8L is normally maintained energized by a circuit closed from (+), 65 through a circuit including front contact 24 of relay 8WS, front contact 25 of relay 8TR, front

contact 26 of relay 8ES, winding of relay 8L, and front contact 27 of relay 8L, to (-).

The route locking relays ES and WS are normally energized directional stick relays that are controlled in a manner similar to that shown, for example, as in the patent to A. Langdon, Patent No. 2,148,865, dated February 28, 1939. If it is required in practice that approach locking be provided, the control of the relays ES and WS can include approach locking in a manner such as is shown, for example, in the patent to C. F. Stoltz, Patent No. 2,115,511, dated April 26, 1938.

Self-selecting network.—As has already been pointed out in a general manner, the self-selecting network consists of two circuit networks. One of the networks is energized responsive to the designation of a route end at a particular end of the track layout as either an entrance or an exit point, and the other circuit network is energized responsive to the designation of a route end at the opposite end of the track layout as either an entrance or an exit point. The designation of the exit end of a route is effective for energizing the circuit network responsive to the designation of that particular route end, only if a route is available between the designated entrance point and that exit point. Included in each circuit network is a normal and a reverse switch control relay for each track switch trailed from the route end from which that circuit network is energized. Thus, two normal and two reverse switch control relays are provided for each crossover, one normal and one reverse switch control relay being provided for the track switch at each end of the crossover. In addition to a normal and a reverse switch control relay provided for each single track switch, there is a relay X provided which is responsive to the energization of the opposite circuit network from the circuit network in which the normal and reverse switch control relays for that track switch are energized. Such relay X is provided for a single track switch in order that execution of the switch controls for a single track switch is dependent upon designation of both entrance and exit points as is required in a route over a crossover.

To consider more specifically how the system provided by the present invention operates, consider, as a typical example, that an operator desires to set up a route from signal A to signal E (see Fig. 3) at a time when the normal conditions of the system exist as they have been described.

The depression of button ANB as designation of the entrance point for such a route (see Fig. 1A) causes the picking up of the entrance relay ANR. When relay ANR is picked up a circuit is closed to cause the picking up of the reverse switch control relay 2BR because that track switch is trailed from the designated entrance point. Upon designation of the exit point the exit relay EXR is picked up, and the picking up of that relay causes the picking up of relay 3R because the single track switch 3TS is trailed from the exit point designated. After that reverse switch control relay is picked up, in accordance with the general principles of the system, namely, that the selection of each track switch to be included in a route is dependent upon both entrance and exit designation, a switch execution relay 3X is picked up to complete the selection of track switch 3TS as being definitely included in the route being selected. The energi-

zation of relay 3X is dependent upon the picked up positions jointly of relays ANR and 3R. After relay 3R is picked up the reverse switch control relay 2AR is picked up to complete the selection of the route, because that track switch is also trailed from the exit point designated.

Having thus outlined the general mode of operation in selecting a route from signal A to signal E, consideration will now be given in detail to the circuits involved in such selection. The depression of button ANB causes the picking up of the entrance relay ANR, for that particular entrance point, by the energization of a circuit closed from (+), through a circuit including contact 28 of button ANB closed in a depressed position, winding of relay ANR, and front contact 29 of relay 7TR, to (-). When relay ANR is picked up, a stick circuit is closed for that relay from (+), through a circuit including contact 28 of button ANB maintained closed in both a normal and a depressed position, front contact 30 of relay ANR, winding of relay ANR, and front contact 29 of relay 7TR, to (-). Responsive to the picking up of relay ANR, a switch control relay is picked up for each track switch trailed in an available route from that designated entrance point, thus, relay 2BR is picked up by the energization of a circuit closed from (+), through a circuit including front contact 31 of relay ANR, back contact 32 of relay AXR, back contact 33 of relay 2AN, back contact 34 of relay 2BN, and upper winding of relay 2BR, to (-). Although energy feeds through the circuit network for switch control relays associated with crossover 4, to cause the energization of some of such relays, in order to confine the description as much as possible to the route assumed to be designated, reference will not be made to the energization of such switch control relays for crossover 4 at this time.

Upon designation of the exit point for signal E by the depression of exit button EXB (see Fig. 1B), the exit relay EXR is picked up by the energization of a circuit closed from (+), through a circuit including front contact 31 of relay ANR, back contact 32 of relay AXR, back contact 33 of relay 2AN, back contact 34 of relay 2BN, front contact 35 of relay 2BR, back contact 36 of relay 2BN, back contact 37 of relay 3N, wire 49, winding of relay EXR, back contact 38 of relay ENR, and contact 39 of button EXB closed in a depressed position, to (-). The picking up of relay EXR closes a stick circuit for that relay at front contact 40 to shunt contacts 38 and 39 out of the circuit just described, such stick circuit being provided in order to maintain relay EXR picked up after the exit button EXB is restored to normal, and to prevent the dropping away of relay EXR if an operator should depress button ENB, for any particular reason, to cause the picking up of relay ENR.

Responsive to the picking up of relay EXR, relay 3R is picked up, because that track switch is trailed from the designated exit point, by the energization of a circuit closed from (+), through a circuit including front contact 41 of relay EXR, wire 42, back contact 43 of relay 3N, and upper winding of relay 3R, to (-).

After relay 3R is picked up, the execution relay 3X for that single track switch is picked up to cause the positioning of track switch 3 in accordance with the reverse control selected upon the picking up of relay 3R. Relay 3X is picked up by the energization of a circuit closed from (+), through a circuit including front contact

31 of relay ANR, back contact 32 of relay AXR, back contact 33 of relay 2AN, back contact 34 of relay 2BN, front contact 35 of relay 2BR, back contact 36 of relay 2BN, front contact 44 of relay 3R, and winding of relay 3X, to (-).

The picking up of relay 3R also causes the picking up of relay 2AR for the track switch at the upper end of crossover 2, because that track switch is trailed from the designated exit point, by the energization of a circuit closed from (+), through a circuit including front contact 41 of relay EXR, wire 42, back contact 43 of relay 3N, front contact 45 of relay 3R, back contact 46 of relay 3N, back contact 47 of relay 2BN, back contact 48 of relay 2AN, and upper winding of relay 2AR, to (-). Upon the picking up of relay 2AR, the track switches of crossover 2R are operated to their reverse positions because the reverse relays 2AR and 2BR are both picked up.

The specific means by which the track switches are actually operated, and the means by which the signal is cleared for the entrance to the route, will be hereinafter considered.

From the above described circuits, it will be readily apparent that the exit relay EXR can be picked up only when there are no positions for track switches, included in the route between that exit point and the designated entrance point, which have their controls already selected by the picking up of the normal switch control relay for operating those track switches to a normal position.

It will also be apparent from the circuits just described that energy can feed through the circuit network for the normal and reverse switch control relays only so far as there are no conflicting positions of the track switches in the route between the track switches associated with such normal and reverse relays and the designated entrance point. That is, energy can be fed through the circuit network to relay 2AR only if the normal switch control relays 2AN and 2BN for that crossover are dropped away to close back contacts 48 and 47 respectively, and only if relay 3N is dropped away to close back contact 46.

When relay 2AR is picked up, responsive to the designation of the exit point in setting up the route from signal A to signal E, a branch of the circuit network for the control of track switches to the right of track switch 2TSA is opened at back contact 50 of relay 2AR to cause any switch control relays energized by that branch of the circuit network to be dropped away, and, in a similar manner, the picking up of relay 3R opens the branch of the circuit network for the control of track switches to the right of track switch 3 at back contact 44 to cause any switch control relays energized by the branch of the circuit network extending to the right of that contact to be dropped away.

Upon the picking up of relay 2AR, responsive to the designation of the exit point, the branch of the circuit network extending from front contact 59 of relay BNR to the center winding of relay 2BN is opened at back contact 61 to prevent the energization of relay 2BN if an operator should designate an entrance point at signal B while the route is set up from signal A to signal E. Back contact 110 of relay 2BR, connected in multiple with back contact 61 of relay 2AR, is open at that time because relay 2BR has been picked up responsive to the designation of the entrance point.

As an example of how the same circuits are used in selecting a route for both directions of

traffic, assume an operator to set up the same route for west bound traffic as has been just described for east bound traffic. Thus, when the normal conditions of the system exist as has been described, assume an operator to designate a route to be set up from signal E to signal A.

The depression of button ENB for designation of the entrance point, causes relay ENR to be picked up, and a stick circuit to be established for that relay by the energization of circuits similar to those described for entrance relay ANR.

Upon the picking up of relay ENR, front contact 53 of relay ENR applies energy to the same circuit just described for relay 3R at back contact 41 of relay EXR. The energization of that circuit causes the picking up of relays 3R and 2AR in a manner similar to that which has been described.

Upon designation of the exit point for such route at signal A by the depression of button AXR, relay AXR is picked up by the energization of a circuit closed from (+), through a circuit including front contact 53 of relay ENR, back contact 41 of relay EXR, wire 42, back contact 43 of relay 3N, front contact 45 of relay 3R, back contact 46 of relay 3N, back contact 47 of relay 2BN, back contact 48 of relay 2AN, front contact 54 of relay 2AR, back contact 55 of relay 2AN, winding of relay AXR, back contact 56 of relay ANR, and contact 57 of button AXB closed in a depressed position, to (-). The picking up of relay AXR closes a stick circuit for that relay at front contact 58 for shunting contacts 56 and 57 out of the circuit just described.

When relay AXR is picked up, the closing of front contact 32 causes energy to be applied to the circuit that has been described for relay 2BR, and, after relay 2BR is picked up to close front contact 35, relay 3X is picked up by energy applied at front contact 32 of relay AXR to the circuit which has also been described for that relay.

The picked up position of relays 2BR and 2AR jointly causes the track switches of crossover 2 to be operated to their reverse positions, and the picked up position of relays 3X and 3R jointly causes track switch 3TS to be operated to a reverse position.

It will be noted that, although the circuits for the relays 2BR, 2AR, 3X and 3R are common for both directions of traffic, the order in which the track switches are definitely selected as being included in the route by the joint energization of a relay responsive to each of the two circuit networks, is dependent upon the direction of traffic designated by an operator. That is, in setting up a route from signal A to signal E, the track switch 3TS is selected first as being definitely included in the route by the joint picked up position of relays 3R and 3X, however, in setting up a route from signal E to signal A, the track switches of crossover 2 are selected first as being definitely included in the route by the joint picked up position of relays 2AR and 2BR.

It will be more readily apparent as the description progresses and the selection of routes including a greater number of track switches is involved, that the definite selection of track switches included in a route in each case begins with the track switch nearest the designated exit point and progresses for the successive track switches toward the designated entrance point, until the route is completely selected.

Another general characteristic feature of the system provided by the present invention is believed to be apparent from the above description.

Such feature is that, responsive to the designation of an entrance point, energy feeds through the circuit network in all directions corresponding to the routes available emanating from that point, while the designation of an exit point confines the energization of the switch control relays in the circuit network to one particular route. The designation of an entrance point at signal A in the example described above, by the picking up of relay ANR, causes energy to feed through the circuit network through back contact 50 of relay 2AR, and through back contact 44 of relay 3R for the energization of other switch control relays for trailed track switches; however, the designation of an exit point at signal A, in the example described above, does not feed energy in the circuit network past contacts 50 and 44 of relays 2AR and 3R respectively because those relays have already been picked up responsive to the designation of an entrance point at signal E.

After having considered the principles involved in setting up routes in which the reverse positions of the track switches are selected, it will now be pointed out how a very similar mode of operation is effected when normal positions of the track switches are selected. A feature that the selection of the normal position for track switches has in common with the selection of a reverse position for track switches, is that, for a crossover, the energization of a normal switch control relay for each end of the crossover is required in order that the switch machine may be operated to a normal position and in order that a track switch of that particular crossover can be included in a normal position in the route selected by the system. One of the normal switch control relays for a crossover is responsive to the designation of the entrance point in setting up a route, and the other normal switch control relay for that crossover is responsive to the designation of an exit point in setting up a route. A much similar mode of operation is followed in selecting the normal position for a single track switch in setting up a route, namely, the normal switch control relay for that track switch is responsive to the designation of either an entrance or an exit point, dependent upon from which it is trailed, and a relay X for that single track switch is dependent for energization upon the designation of the opposite end of the route being set up, the picking up of the relay X in combination with the relay N for the single track switch is used as an executing means for causing the operation of the track switch.

As an example of how a route is selected in which the normal position of a track switch is involved, assume, at a time when the normal conditions of the system exist as described, that an operator desires to set up a route from signal B to signal E. The depression of entrance button BNB for designation of the entrance point of the route, causes the picking up of relay BNR by the energization of a circuit similar to that described for the picking up of relay ANR, and such entrance relay is maintained picked up dependent upon the track relay 8TR maintained energized.

Responsive to the picking up of relay BNR, relay 2BN is picked up by the energization of a circuit closed from (+), through a circuit including front contact 59 of relay BNR, back contact 60 of relay BXR, back contact 61 of relay 2AR, and center winding of relay 2BN, to (-). Upon designation of the exit point at 75

signal E by the depression of button EXR, relay EXR is picked up by the energization of a circuit closed from (+), through a circuit including front contact 59 of relay BNR, back contact 60 of relay BXR, back contact 61 of relay 2AR, front contact 36 of relay 2BN, back contact 37 of relay 3N, wire 49, winding of relay EXR, back contact 38 of relay ENR, and contact 39 of button EXB closed in a depressed position, to (-). The picking up of relay EXR closes a stick circuit at front contact 40 for shunting contacts 38 and 39 out of the circuit just described.

Responsive to the picking up of relay EXR, relay 3R is picked up by the energization of a circuit which has been described, and the picking up of relay 3R closes a circuit for relay 3X extending from (+), through a circuit including front contact 59 of relay BNR, back contact 60 of relay BXR, back contact 61 of relay 2AR, front contact 36 of relay 2BN, front contact 44 of relay 3R, and winding of relay 3X, to (-).

The picking up of relay 3R causes the picking up of relay 2AN by the energization of a circuit closed from (+), through a circuit including front contact 41 of relay EXR, wire 42, back contact 43 of relay 3N, front contact 45 of relay 3R, back contact 46 of relay 3N, front contact 47 of relay 2BN, and upper winding of relay 2AN, to (-). The picking up of relay 2AN definitely determines that one of the track switches of crossover 2 is to be included in the route which has been definitely selected up to that point, and thus, with relays 2AN and 2BN picked up, the track switches of the crossover over 2 are operated to corresponding positions.

It will be noted from the above described example, that, in setting up a route from signal B to signal E, relay 2BN is responsive to the designation of the entrance point, and relay 2AN is responsive to the designation of the exit point in setting up that route. If, however, the same route is set up for west bound traffic, that is, from signal E to signal B, relay 2BN is picked up responsive to the designation of the exit point 45 when energy is applied to the circuit which has been described for that relay, and relay 2AN is picked up after relay 2BN is picked up, dependent upon energy fed through the circuit network extending from the entrance relay ENR.

To consider in a more specific manner how the normal switch control relays are energized for crossover 2 in setting up a route from signal E to signal B, assume an operator to designate such a route at a time when the normal conditions of the system exist. The designation of the entrance point at signal E causes the picking up of relay ENR, and the picking up of that relay causes the picking up of relay 3R by the energization of a circuit which has been described.

Upon designation of the exit point for that route by the depression of button BXB, relay BXR is picked up by the energization of a circuit closed from (+), through a circuit including front contact 53 of relay ENR, back contact 41 of relay EXR, wire 42, back contact 43 of relay 3N, front contact 45 of relay 3R, back contact 46 of relay 3N, back contact 62 of relay 2BR, winding of relay BXR, back contact 63 of relay BNR, and contact 64 of button BXB closed in a depressed position, to (-). The picking up of relay BXR closes a stick circuit for that relay at front contact 65 to shunt contacts 63 and 64 out of the circuit just described.

After relay BXR is picked up, relay 2BN is picked up when energy is applied at front contact 60 to a circuit which has been described. When relay 2BN is picked up, relay 2AN is picked up by the energization of a circuit closed from (+), through a circuit including front contact 53 of relay ENR, back contact 41 of relay EXR, wire 42, back contact 43 of relay 3N, front contact 45 of relay 3R, back contact 46 of relay 3N, front contact 47 of relay 2BN, and upper winding of relay 2AN, to (-).

It will be noted that in the selection of a route which includes a track switch in a normal position, the selection of the track switches as being definitely included in a route selected between the entrance and exit points designated, is effected in a cascade order, one track switch or one small group of track switches at a time, starting with the track switch nearest the designated exit point the same as was pointed out in describing the setting up of routes including the track switches in their reverse positions.

It is believed from the above typical examples and general description of the mode of operation of the normal and reverse switch control relays of the various routes, that it will be readily apparent to those familiar with the art how the system can be expanded to satisfy any particular track layout encountered in practice. It will be pointed out, however, hereinafter, how the system satisfies particular conditions encountered in practice with respect to the selection of a preferred one of several optional routes.

Switch control.—Although the normal and reverse switch control relays select the position to which their respective track switches are to be operated, as has been pointed out in a general manner, the normal and reverse switch control relays for each track switch are not effective for causing the positioning of that track switch unless there has been a relay for that track switch energized in each of the two circuit networks for that interlocked group, one relay being energized dependent upon the entrance point designated, and the other relay being energized dependent upon the exit point designated. It has also been pointed out that, in setting up a route, the track switches are selected as being definitely determined to be included in that route in succession, one track switch or one small group of track switches at a time, starting with the track switch nearest the designated exit point. Thus, if each of the track switches is operated to the selected position dependent upon both entrance and exit point designation, and the definite selection of a track switch is dependent upon the complete selection of the route up to that track switch from the exit point designated, the track switches are initiated into operation in succession, one track switch or one small group of track switches at a time, starting with the track switch nearest the designated exit point.

Inasmuch as the switch control circuits are similar for the control of each of the track switches, the control circuits shown in Fig. 2 can be considered as typical of the circuits provided for the control of each of the other switch machines. Thus, to consider the mode of operation of the typical switch control system as shown in Fig. 2, assume, for example, that a route has been selected by the normal and reverse switch control relays as has been described from signal A to signal E. Under such conditions, relays 2AR and 2BR are picked up, relay 2BR being picked up responsive to the designation of the

entrance point at signal A, and relay 2AR being picked up responsive to the designation of the exit point at signal E.

After relays 2AR and 2BR have both been picked up, assuming the prior position of the track switches of the crossover to be normal as illustrated in Fig. 2, the lower winding of relay 2WZ is energized to cause that relay to be picked up with its polar contacts operated to a left hand position. In accordance with the picking up of relay 2WZ, the switch machine 2SM is operated to its reverse position in correspondence with the controls selected for that switch machine. After the switch machine has completed its operation, the polar contacts of the switch repeater relay 2WP are operated to their left hand positions in correspondence with the reverse locked positions of the switch machine 2SM and the track switches 2TSA and 2TSB, thus opening the circuit for the relay 2WZ and causing that relay to be dropped away. The dropping away of relay 2WZ deenergizes the switch machine control circuit, and causes the picking up of a correspondence relay 2RCR which repeats the reverse position of the contacts of relay 2WP in correspondence with the picked up position of the reverse switch control relays 2AR and 2BR. When relay 2RCR is picked up, a branch of the circuit network for the control of the signal control relays G is closed to indicate that the track switches have been properly positioned for the crossover 2 in the particular route selected.

To consider more specifically how the circuits provide such a mode of operation, assuming relays 2AR and 2BR to be picked up under the conditions described above, the lower winding of relay 2WZ is energized by a circuit closed from (+), through a circuit including front contact 66 of relay 2AR, front contact 67 of relay 2BR, polar contact 68 of relay 2WP in a right hand position, front contact 69 of relay 7L, front contact 70 of relay 8L, back contact 71 of relay 2NCR, and lower winding of relay 2WZ, to (-). Responsive to such energization relay 2WZ is picked up with its polar contacts operated to a left hand position and closes front contact 72 to provide the energization of an obvious circuit for operating the switch machine 2SM to a reverse position.

When the switch machine has completed its operation to a reverse position and the relay 2WP is picked up with its polar contacts operated to a left hand position, relay 2WZ is dropped away because of the opening of polar contact 68 of relay 2WP in a right hand position. When relay 2WZ has dropped away, the correspondence relay 2RCR is picked up by the energization of a circuit closed from (+), through a circuit including front contact 66 of relay 2AR, front contact 67 of relay 2BR, polar contact 68 of relay 2WP in a left hand position, front contact 73 of relay 2WP, back contact 74 of relay 2WZ, and winding of relay 2RCR, to (-). The control circuit for the switch machine 2SM is of course opened at front contact 72 of relay 2WZ upon the dropping away of that relay.

If the track switches 2TSA and 2TSB are in reverse positions at a time when the reverse control of those track switches is selected by the picking up of relays 2AR and 2BR, relay 2WZ is not picked up, because of its pick-up circuit being opened at polar contact 68 of relay 2WP, and the correspondence relay 2RCR is picked up, immediately following the picking up of the second of the two reverse switch control relays for

that crossover, by the energization of the circuit just described for that relay.

To consider the circuits by which the switch machine 2SM is operated from a reverse position to a normal position, assume the track switches 2TSA and 2TSB to be in their reverse locked position when the normal position of such track switches is selected by the picking up of relays 2AN and 2BN, as is effected in setting up a route from signal B to signal E. When relays 2AN and 2BN are picked up, relay 2WZ is picked up by the energization of a circuit closed from (+), through a circuit including front contact 75 of relay 2AN, front contact 76 of relay 2BN, polar contact 77 of relay 2WP closed in a left hand position, front contact 78 of relay 7L, front contact 79 of relay 8L, back contact 80 of relay 2RCR, and upper winding of relay 2WZ, to (-). When relay 2WZ is picked up responsive to the energization of that circuit, energy is applied to the switch machine 2SM at front contact 72 to cause the operation of that switch machine to a normal position in correspondence with the position selected by the normal switch control relays 2AN and 2BN. After the track switches 2TSA and 2TSB have been operated to their reverse positions and locked in correspondence with the switch machine 2SM, the relay 2WP is picked up with its polar contacts operated to a right hand position, thus opening the pick-up circuit just described for relay 2WZ at polar contact 77 in a left hand position, to cause relay 2WZ to be dropped away. Upon the dropping away of relay 2WZ energy is removed from the switch machine control circuit and the correspondence relay 2NCR is picked up by the energization of a circuit closed from (+), through a circuit including front contact 75 of relay 2AN, front contact 76 of relay 2BN, polar contact 77 of relay 2WP closed in a right hand position, front contact 81 of relay 2WP, back contact 82 of relay 2WZ, and winding of relay 2NCR, to (-). The picking up of relay 2NCR closes the portion of the signal control circuit network associated with crossover 2 as is shown in Fig. 3 and hereinafter described.

If the track switches 2TSA and 2TSB are in their normal positions as shown when the normal position of such track switches is selected by the picking up of relays 2AN and 2BN, relay 2NCR will be energized upon the picking up of those relays because the pick-up circuit of relay 2WZ would be open under such conditions at polar contact 77 in a left hand position.

To provide that the track switches will complete their operation, once the operation of the switch machine is selected by the picked up position of relay 2WZ, when the normal position for those track switches is selected, even if the normal switch control relays 2AN and 2BN are dropped away prior to the completion of the operation, a stick circuit is provided for relay 2WZ, closed from (+), through a circuit including front contact 83 of relay 2WZ, polar contact 84 of relay 2WZ closed in a right hand position, back contact 85 of relay 2BR, back contact 86 of relay 2AR, polar contact 77 of relay 2WP in a left hand position, front contact 78 of relay 7L, front contact 79 of relay 8L, back contact 80 of relay 2RCR, and upper winding of relay 2WZ, to (-).

A stick circuit is also provided in order that the track switches 2TSA and 2TSB will be operated to their reverse positions, when such control is selected by the relay 2WZ, irrespective of

the position of relays 2AR and 2BR, closed from (+), through a circuit including front contact 83 of relay 2WZ, polar contact 84 of relay 2WZ in a left hand position, back contact 87 of relay 5 2AN, back contact 88 of relay 2BN, polar contact 68 of relay 2WP in a right hand position, front contact 69 of relay 7L, front contact 70 of relay 8L, back contact 71 of relay 2NCR, and lower winding of relay 2WZ, to (-).

- 10 In order that the track switches 2TSA and 2TSB can be biased to their positions last selected by the normal and reverse switch control relays, it is provided that, should the track switches 2TSA and/or 2TSB become unlocked 15 from the positions previously selected by the relays 2AN and 2BN, relay 2WZ is picked up by the energization of a circuit closed from (+), through a circuit including back contact 89 of relay 2WP, polar contact 84 of relay 2WZ in a right hand position, back contact 85 of relay 2BR, back contact 86 of relay 2AR, polar contact 77 of relay 2WP in a right hand position, back contact 81 of relay 2WP, front contact 78 of relay 7L, front contact 79 of relay 8L, back contact 80 of relay 2RCR, and upper winding of relay 2WZ, to (-). The picking up of relay 2WZ due to the energization of that circuit would cause the switch machine 2SM to be operated back to a normal locked position.
- 20 30 If the track switches 2TSA and 2TSB should become unlocked from their last selected reverse position, relay 2WZ would be picked up to cause the switch machine 2SM to be operated back to a reverse locked position, by the energization of a circuit closed from (+), through a circuit including back contact 89 of relay 2WP, polar contact 84 of relay 2WZ in a left hand position, back contact 87 of relay 2AN, back contact 88 of relay 2BN, polar contact 68 of relay 2WP in a left hand position, back contact 73 of relay 2WP, front contact 69 of relay 7L, front contact 70 of relay 8L, back contact 71 of relay 2NCR, and lower winding of relay 2WZ, to (-).
- 35 40 It is believed that it will be obvious from the above described circuits that, if a track switch is moved, for example, from its normal position to its reverse position by a maintainer hand cranking the switch machine 2SM, the dropping away of the relay 2WP during such operation causes the picking up of relay 2WZ as has been described, and the closing of the stick circuit for relay 2WZ at front contact 83 which is connected in multiple with back contact 89 of relay 2WP, provides that, whenever the power operation 45 of the switch machine is rendered effective by the closing of the crank contact in the switch machine by the maintainer, the switch machine 2SM will be operated back to its normal position by power operation, even if it has been hand cranked to a reverse locked position to cause the picking up of relay 2WP. It is believed that it will be obvious that a similar mode of operation is effected whereby the track switch can be restored to a reverse position if such position has been selected prior to the hand cranking of the switch machine 2SM to a normal position.

In addition to the control of the normal and reverse switch control relays, responsive to the designation of the ends of each route, it is provided that the track switches for each crossover and each single track switch can also be positioned by actuation of an auxiliary switch control lever SML for that particular crossover or single track switch. Thus, the relays 2AN, 2BN,

2AR and 2BR, as a typical example, are responsive to the positioning of the auxiliary switch control lever 2SML. If an operator desires to cause the operation of the track switches 2TSA and 2TSB to a normal or a reverse position, by positioning the auxiliary switch control lever 2SML, he can cause such operation by actuating that lever from the normal center position to an upper or a lower operating position in accordance with the normal or reverse position desired for the track switches 2TSA and 2TSB.

To consider an example of how a track switch can be positioned by the operation of the control lever 2SML, assume that an operator moves the lever 2SML to a reverse operating position, at a time when the normal conditions of the system exist as have been described. Such operation causes the contacts associated with lever 2SML to be operated to a left hand position to close a circuit for causing the picking up of relay 2AR, from (+), through a circuit including contact 90 of lever 2SML closed in a left hand position, back contact 91 of relay 2AN, back contact 92 of relay 2BN, and lower winding of relay 2AR, to (-). Upon the picking up of relay 2AR, relay 2BR is picked up by the energization of a circuit closed from (+), through a circuit including contact 90 of lever 2SML closed in a left hand position, back contact 91 of relay 2AN, back contact 92 of relay 2BN, front contact 93 of relay 2AR, and lower winding of relay 2BR, to (-). In accordance with the picking up of relays 2AR and 2BR, the switch machine 2SM is operated to a reverse position in the same manner as has been described.

If, when the track switches 2TSA and 2TSB are reverse, an operator moves the lever 2SML to a normal operating position to cause the contacts associated with that lever to be operated to the right, relay 2AN is picked up by the energization of a circuit closed from (+), through a circuit including contact 90 of lever 2SML in a right hand position, back contact 94 of relay 2AR, back contact 95 of relay 2BR, and lower winding of relay 2AN, to (-). When relay 2AN is picked up, relay 2BN is picked up by the energization of a circuit closed from (+), through a circuit including contact 90 of lever 2SML in a right hand position, back contact 94 of relay 2AR, back contact 95 of relay 2BR, front contact 96 of relay 2AN, and lower winding of relay 2BN, to (-). Responsive to the picking up of relays 2AN and 2BN, the switch machine 2SM is operated to a normal position in the same manner as has been described.

If, for some reason, such as obstruction at the switch points, the operation of a track switch cannot be completed after the switch machine has been set into operation, an operator can cause the restoration of that track switch to its former position by causing the energization of the switch control relays for the corresponding desired position of that track switch. That is, for example, if the relays 2AR and 2BR have been picked up and the switch machine 2SM has been partially operated from its normal to its reverse position and the complete operation of that switch machine is obstructed, an operator, upon causing the dropping away of relays 2AR and 2BR and the picking up of relays 2AN and 2BN, can cause the switch machine 2SM to be restored to its original normal position. Such operation is effected because the picking up of the relays 2AN and 2BN opens the stick circuit described for relay 2WZ at back contacts 87 and

88 respectively, thus allowing relay 2WZ to be dropped away and energized with the opposite polarity in accordance with the normal switch control relays 2AN and 2BN picked up.

If it is not required in practice that the bias feature of the switch control circuits be provided, back contact 89 of relay 2WP can be eliminated and back contacts 87, 88, 86 and 85 of relays 2AN, 2BN, 2AR and 2BR respectively 5 are no longer required in the stick circuits for relay 2WZ, because reversal in midstroke can be accomplished by causing relay 2WZ to be dropped away upon energization of both windings with opposite polarity. Upon the dropping away of the relay 2WZ, under such conditions, the winding energized in the stick circuit of the relay 2WZ is deenergized, thus causing the polar contacts to be operated to the opposite position and the relay to be picked up for causing the 10 operation of the switch machine back to its former locked position.

In Fig. 6 of the accompanying drawings, a typical single switch control circuit is shown for the track switch 3TS of the track layout shown in Fig. 3. The control circuits shown in this Fig. 6 are similar to those shown in Fig. 2 and their operation will not be described in detail. It is noted that the lock relay 8L¹ is controlled by the directional stick relays 8ES, 8TR and 8WS by contacts 230, 231 and 232 respectively, in a similar manner as the lock relay 8L of Fig. 2 is controlled through contacts 26, 25 and 24 of the same relays. The lock relay 8L¹ is provided with a stick contact 233 15 which is used to shunt out the lever contact 234 of the lever 3SML.

The operation of the lever 3SML, of course, operates its contact 235 to either the normal or the reverse position to energize the corresponding normal or reverse control relay 3N or 3R. The picking up of the normal control relay 3N or the reverse control relay 3R upon the operation of the lever 3SML passes energy on to the execution relay 3X to energize it. The energization of this exit relay 3X then completes the normal or reverse control circuit as selected by the particular normal or reverse control relay 3N or 3R then picked up. It is, of course, understood that the execution relay 3X is also picked up with either the normal or the reverse control relay through the medium of the selecting circuits as shown and described in connection with Figs. 1A and 1B. It is believed that further operation of the circuits shown in Fig. 6 will be obvious from the consideration of the drawings in view of the description given in connection with Fig. 2.

Signal controls.—The signal control relays G which govern the indication of the signals are energized by a signal control circuit network 20 as is shown, for example, in Fig. 3 for the track layout illustrated in that figure. The same circuit network is used for energizing signal control relays for controlling west bound traffic as is used for energizing signal control relays for east bound traffic.

As a typical example of the means by which each of the signal control relays G is energized, consider, for example, that a route has been selected from signal A to signal E and that the track switches 2TSA, 2TSB and 3TS have been properly positioned for that route. When the track switches 2TSA and 2TSB have been positioned for that route the correspondence relay 2RCR is picked up, and when the track

switch 3TS has been positioned for that route the correspondence relay 3RCR is picked up. The picking up of relay 2RCR closes the circuit for the signal control relay AG, from (+), through a circuit including front contact 97 of relay EXR, front contact 98 of relay 3RCR, back contact 99 of relay 3NCR, front contact 100 of relay 2RCR, back contact 101 of relay 2NCR, back contact 102 of relay AXR, front contact 103 of relay ANR, and winding of relay AG, to (-). The picking up of relay AG opens back contact 104 to cause the red lamp in signal A to be extinguished and closes front contact 104 to cause the green lamp in signal A to be illuminated.

It is believed that it will be obvious that the signal control relay EG can be picked up, after a route is set up from signal E to signal A by the energization of a circuit including the same contacts of the correspondence relays as were described as being included in the control circuit for relay AG, energy being supplied under such conditions by front contact 102 of relay AXR.

To consider as another typical example how the signal control relays G are controlled, assume that a route has been selected as heretofore described from signal B to signal E, and that the track switches have been positioned in accordance with their required positions for such route. The picking up of relay 2NCR, after the track switches 2TSA and 2TSB have been operated to their normal locked positions, causes the picking up of relay BG by the energization of a circuit closed from (+), through a circuit including front contact 97 of relay EXR, front contact 98 of relay 3RCR, back contact 99 of relay 3NCR, back contact 100 of relay 2RCR, front contact 105 of relay 2NCR, back contact 106 of relay BXR, front contact 107 of relay ENR, and winding of relay BG, to (-). The opening of back contact 108 of relay BG causes the extinguishing of the red lamp in signal B, and the closing of front contact 108 causes the illumination of the green lamp in signal B.

Restoration to normal.—Once the route establishing means is energized for setting up a route, it is maintained energized as long as the entrance relay for the entrance to that route is maintained picked up. Each of the entrance relays is maintained energized dependent for deenergization upon passage of a train passed the signal at that entrance point, or dependent for deenergization upon the pulling out of the entrance button NB for that particular entrance point. Other means dependent upon the route locking is provided for maintaining the route establishing means effective for the portion of each route in advance of each train after that train accepts the entering signal to that route in a manner which is herein-after described when considering more in detail the route locking provided and the means provided for the prevention of the preconditioning of routes.

To consider as a specific example of how the route establishing means is restored to normal responsive to manual control, assume an operator to initiate the restoration of the route establishing means for a route which has been set up from signal A to signal E.

Upon the pulling out of button ANB, under such conditions (see Fig. 1A), relay ANR is dropped away by the opening of normally closed contact 28. When relay ANR is dropped away, relay EXR is dropped away because 75

of the opening of front contact 31 of relay ANR, and at the same time the signal control relay AG is dropped away because of the opening of front contact 103 of relay ANR (see Fig. 3).

5 When the signal control relay AG is dropped away, the normally energized route locking relays 7ES and 8ES (see Fig. 2) are picked up, and the picking up of those relays closes pick-up circuits for the relays 7L and 8L. The pick-up circuit for relay 7L is closed from (+), through a circuit including front contact 20 of relay IWS, front contact 21 of relay 7TR, front contact 22 of relay 7ES, winding of relay 7L, and contact 109 of lever 2SML in a normal position, to (-). The picking up of relay 7L closes a stick circuit for that relay at front contact 23 to provide the restoration of that relay to the normal conditions as have been described. The relay 8L is picked up by the energization of a pick-up circuit provided in a similar manner to the pick-up circuit just described for relay 7L.

The pick-up circuit for relay 2BR is opened at front contact 31 of relay ANR when that relay is dropped away, and the dropping away of relay EXR opens the pick-up circuit for relays 3R and 2AR at front contact 41 (see Fig. 1B). After such pick-up circuits for the relays 2BR, 2AR and 3R are opened, those relays are dropped away as soon as the lock relays L for those track switches have been picked up to open stick circuits hereinafter described for such reverse switch control relays.

25 The correspondence relays 2RCR and 3RCR (see Fig. 3) are dropped away, responsive to the dropping away of the reverse switch control relays for their associated track switches. Relay 2RCR is dropped away by the opening of front contacts 66 and 67 of relays 2AR and 2BR respectively (see Fig. 2).

30 In a similar manner the route establishing means associated with each of the various routes can be restored to normal at the will of an operator by the pulling out of the button for the entrance point to that particular route.

If the route establishing means for the route 45 from signal A to signal E is to be automatically restored upon passage of a train, a similar mode of operation to that just described is effected. The entrance relay NR for the entrance point to that route is dropped away when the train passes the signal because of the opening of the stick circuit for that relay at front contact 29 of relay 7TR (see Fig. 1A), and the pick-up circuits for the reverse switch control relays are opened in the same manner as has been described, but the 50 reverse switch control relays are maintained picked up by their stick circuits until the detector track sections for those track switches become unoccupied in the rear of the passing train. The means by which such stick circuits are provided will be hereinafter described more in detail when 55 considering the means provided for the prevention of the preconditioning of routes.

Route locking.—Inasmuch as this invention is more particularly related to the novel features provided by the route selecting and route establishing means, it is believed to be unnecessary to show and describe the details of the circuits by which route locking and approach locking can be provided for the system shown, as is shown in the patent to A. Langdon, Patent No. 2,148,865, dated February 28, 1939, for the detailed circuits of a system of route locking that can be used with the system provided by the present invention. If, in addition to the route locking, approach locking is

required, the approach and route locking can be provided in a manner, for example, such as is shown in the patent to C. F. Stoltz, Patent No. 2,115,511, dated April 26, 1938.

The directional stick relays ES and WS used in this disclosure are comparable to the relays bearing similar nomenclature as shown in the above mentioned prior patents to C. F. Stoltz and A. Langdon. Each of the route locking relays ES and WS is provided for a particular detector track section for a particular direction of traffic, and it is dropped away upon setting up a route through that track section in the particular direction for which that route locking relay is provided. The general arrangement of the circuits is such that a route locking relay is dropped away for each track section included in a route established in advance of a train, for that particular direction, and the route locking relays are picked up for the track sections as they become uncoupled in the rear of a train.

Prevention of preconditioning.—Once a route has been completely set up through a track layout, it is impossible to set up a route conflicting with the route already established, and furthermore, it is impossible to so condition that conflicting route that it will be set up automatically as soon as that route is made available by the restoration of the conflicting route previously established. Such mode of operation is desirable in practice particularly in order that the momentary loss of shunt of a track relay cannot cause the operation of a track switch under a train to a position other than the position required for the route established.

To consider an example of how the prevention of the setting up of conflicting routes, and the prevention of the preconditioning of routes is accomplished, assume that a route has been set up as has been described from signal A to signal E (see Figs. 1A and 1B), and also consider that, after the route is established from signal A to signal E, an operator designates signal A to signal E, an entrance point for a conflicting route from signal B to signal D. The designation of signal B as an entrance point causes the picking up of the entrance relay BNR, and the picking up of that relay closes front contact 59 to cause energy to be applied to the circuit network to feed through the network toward the exit relay DXR which must be picked up responsive to the designation of an exit point if the route or any track switch in the route is to be completely selected. Relay DXR cannot be picked up, however, because energy can feed from front contact 59 of relay BNR through the circuit network only so far as back contacts 61 and 110 of relays 2AR and 2BR respectively, because those relays are picked up at that time to correspond with the route set up from signal A to signal E. Thus, it is not only impossible to complete the selection of the conflicting route from signal B to signal D, but it is further provided that the switch control relays 2AN and 2BN cannot be conditioned for crossover 2, and the relay 3N cannot be conditioned for track switch 3, for the route from signal B to signal D, because the circuit for relay 2BN is opened at back contacts 61 and 110 of relays 2AR and 2BR, the circuit for relay 2AN and the circuit for relay 3N are held open because of the failure of relay DXR to be picked up responsive to the designation of the exit point at signal D to close front contact 128 of that relay and feed energy

through the circuit network toward the relays 3N and 2AN.

It is, of course, desirable to maintain such means for prevention of preconditioning of the route from signal B to signal D as long as a portion of that route conflicts with a route maintained established by the route locking, thus, when a train accepts signal A, in proceeding through the route set up from signal A to signal E, it is provided that the reverse relays 2AR and 2BR are maintained picked up because that crossover has its track switches maintained locked by the detector and route locking. Inasmuch as the normal and reverse switch control relays are maintained energized, dependent upon the locked condition of the track switches, the picked up position of the relays 2AR and 2BR as maintained by the presence of the train in track section 1T and in track section 8T provides the same means for the prevention of the preconditioning of a conflicting route by holding open contacts 61 and 110 of relays 2AR and 2BR respectively as has just been described.

To consider the circuits in detail by which the relays 2AR and 2BR are maintained picked up dependent upon the electric locking, with reference to Fig. 2, assume a route has been set up from signal A to signal E and the entering signal A has been cleared. The clearing of signal A causes the dropping away of the relays 7L and 8L because of the dropping away of relays 7ES and 8ES to open respectively front contacts 22 and 26. When relay 7L is dropped away, a stick circuit is closed for relay 2BR from (+), through 35 a circuit including back contact 112 of relay 7L, front contact 113 of relay 2BR, and lower winding of relay 2BR, to (-). A stick circuit is also closed at that time for relay 2AR from (+), through a circuit including back contact 112 of relay 7L, front contact 113 of relay 2BR, front contact 93 of relay 2AR, and lower winding of relay 2AR, to (-). The dropping away of relay 8L closes back contact 114 to supply energy to those stick circuits in multiple with back contact 112 of relay 7L, thus, when relay 7L is picked up as the section 1T is released in the rear of the train, the stick circuits for relays 2AR and 2BR are still maintained energized by back contact 114 of relay 8L. As the train leaves track section 8T, the picking up of relay 8L releases the stick circuits for relays 2AR and 2BR by opening back contact 114 to cause those relays to drop away, and thus allow the crossover 2 to have its track switches positioned in accordance with the next route in which those track switches are to be included.

In a similar manner, the relays 2AN and 2BN are maintained picked up dependent upon the locked condition of the track switches 2TSA and 2TSB. When a signal has been cleared for a route including the track switches 2TSA and 2TSB in normal positions, and the route locking has become effective, a stick circuit is closed for relay 2BN, from (+), through a circuit including either back contact 112 of relay 7L or back contact 114 of relay 8L, as the case may be, front contact 149 of relay 2BN, and lower winding of relay 2BN, to (-). At the same time a stick circuit is closed for relay 2AN, from (+), through a circuit including back contact 112 of relay 7L, or back contact 114 of relay 8L, as the case may be, front contact 149 of relay 2AN, front contact 96 of relay 2AN, and lower winding of relay 2AN, to (-).

It is also provided that the preconditioning of positions of track switches cannot be effected by the positioning of the auxiliary switch control lever SML for a track switch that is already locked in a conflicting position. That is, for example, if the track switches 2TSA and 2TSB are electrically locked in their reverse positions by the dropped away position of relay 7L and/or relay 8L, at a time when an operator positions the lever 2SML in a normal operating position, the positioning of that lever cannot cause the operation of the track switches 2TSA and 2TSB to normal positions after the track sections 7T and 8T have been released by the route locking, because the lock relays 7L and 8L can be picked up only when the lever 2SML is in its normal center position. It is therefore provided, that, in order to cause the operation of the track switches 2TSA and 2TSB to a normal position in accordance with the positioning of the lever 2SML, the lock relays 7L and 8L must be picked up prior to the operation of the lever 2SML from its center position to the desired operating position.

It is believed that it will be readily understood how the conditions described in detail for the control of the track switches 2TSA and 2TSB is typical of similar conditions for each of the other track switches in the track layout.

Optional route selection.—In conditions where optional routes are involved, the system automatically selects the preferred route, in accordance with the arrangement of the circuits. If it is predetermined that the system selects as the preferred route, the route diverging nearest the designated entrance point (except when run-around routes are involved) the circuits are provided as is typically shown in Figs. 1A and 1B, however, if it is predetermined that a particular route shall be preferred, irrespective of whether or not it diverges nearest the designated entrance point, the circuits will be provided as shown in Figs. 1A and 1B except that the circuits for the switch control relays, for the track switch which is in its reverse position, to select the preference, will be provided in accordance with the circuits shown for crossover 4 in Fig. 4. Thus, as typical examples of how optional routes are selected, Figs. 1A and 1B illustrate how preference can be given the route extending from signal A to signal D via crossover 2, and, for a similar track layout, Figs. 1A and 4, when used in combination, illustrate how preference can be given the route from signal A to signal D via crossover 4.

With reference to Figs. 1A and 1B, to consider the means by which crossover 2 is given preference over crossover 4 in selecting a route extending from signal A to signal D, assume that an operator designates an entrance point at signal A by the depression of button ANB, at a time when the normal conditions of the system exist as they have been described. The picking up of relay ANR responsive to such designation causes energy to feed through the circuit network energized from that particular end of the track layout to cause the picking up of relay 2BR, because that track switch is trailed from the designated entrance point, and to cause the picking up of relay 4BN because the track switch with which that relay is associated can be trailed in a normal position from the designated entrance point. That same track switch, however, can be trailed in a reverse position in an available route from the designated entrance point,

- so, in accordance with the general principles upon which the system is based, the relay 4BR would become picked up. However, because it is desirable that the track switches associated with the crossover 4 shall be in the normal position if a route is available over crossover 2 between signal A and signal D, the normal switch control relay 4BN is given preference over the reverse switch control relay 4BR by means of the circuit selections. That is, if relay 4BR is picked up responsive to the designation of an entrance point at signal A, prior to the picking up of relay 4BN responsive to the designation of that entrance point, the relay 4BR will not prevent the picking up of relay 4BN, but the picking up of relay 4BN will effect the dropping away of relay 4BR, or prevent the picking up of relay 4BR, if such relay has not yet been picked up responsive to the entrance point designated.
- Thus, when the track layout includes a greater number of crossovers than those shown, the circuits for each of the crossovers provide the same sort of preference for the normal switch control relays over the reverse switch control relays as has just been described in a general manner for the crossover 4.

To consider how the circuits provide the mode of operation described in a general manner above, assume that an operator designates an entrance point at signal A to cause the picking up of relay ANR (see Fig. 1A) at a time when the normal conditions exist as they have been described. The picking up of relay ANR causes the picking up of relay 2BR by the energization of a circuit which has already been described. Relay 4BR is also picked up responsive to the picking up of relay ANR, by the energization of a circuit closed from (+), through a circuit including front contact 31 of relay ANR, back contact 32 of relay AXR, back contact 50 of relay 2AR, wire 115, back contact 116 of relay 4AN, back contact 117 of relay 4BN, and upper winding of relay 4BR, to (-).

When relay 2BR is picked up, a circuit is closed to cause the picking up of relay 4BN from (+), through a circuit including front contact 31 of relay ANR, back contact 32 of relay AXR, back contact 33 of relay 2AN, back contact 34 of relay 2BN, front contact 35 of relay 2BR, back contact 36 of relay 2BN, back contact 44 of relay 3R, wire 118, back contact 119 of relay 4AR, and center winding of relay 4BN, to (-). Upon the picking up of relay 4BN, relay 4BR is dropped away because of the opening of the circuit just described for that relay at back contact 117.

Upon designation of the exit point at signal D, following the designation of an entrance point at signal A, relay DXR is picked up by the energization of a circuit closed from (+), through a circuit including front contact 31 of relay ANR, back contact 32 of relay AXR, back contact 33 of relay 2AN, back contact 34 of relay 2BN, front contact 35 of relay 2BR, back contact 36 of relay 2BN, back contact 44 of relay 3R, wire 118, back contact 119 of relay 4AR, front contact 120 of relay 4BN, winding of relay DXR, back contact 121 of relay DNR, and contact 122 of button DXB closed in a depressed position, to (-). The picking up of relay DXR closes a stick circuit for that relay at front contact 123 for shunting contacts 121 and 122 out of the circuit just described.

Responsive to the picking up of relay DXR, relay 4AN is picked up, because relay 4BN has

been picked up previously to select such control, by the energization of a circuit closed from (+), through a circuit including front contact 128 (see Fig. 4B) of relay DXR, front contact 129 of relay 4BN, and upper winding of relay 4AN, to (-). When relay 4AN is picked up, it is definitely determined that the track switches of crossover 4 shall be operated to their normal positions, and the track switches are operated to such positions in accordance with the energization of circuits similar to those shown and described as typical in Fig. 2.

After relay DXR is picked up, relay 3N is picked up by the energization of a circuit closed from (+), through a circuit including front contact 128 of relay DXR (see Fig. 1B), back contact 130 of relay 4BR, wire 131, back contact 132 of relay 3R, and upper winding of relay 3N, to (-). After relay 3N is picked up, relay 3X is picked up by the energization of a circuit closed from (+), through a circuit including front contact 31 of relay ANR, back contact 32 of relay AXR, back contact 33 of relay 2AN, back contact 34 of relay 2BN, front contact 35 of relay 2BR, back contact 36 of relay 2BN, front contact 37 of relay 3N, and winding of relay 3X, to (-). The picking up of relay 3X definitely determines that the track switch 3 is required in a normal position in the route selected, and causes the operation of the switch machine for that track switch to a corresponding position.

After relay 3N is picked up, relay 2AR is picked up by the energization of a circuit closed from (+), through a circuit including front contact 128 of relay DXR (see Fig. 1B), back contact 130 of relay 4BR, wire 131, back contact 132 of relay 3R, front contact 46 of relay 3N, back contact 47 of relay 2BN, back contact 48 of relay 2AN, and upper winding of relay 2AR, to (-). The picking up of relay 2AR definitely determines that the track switches of the crossover 2 are to be included in their reverse positions in the route selected from signal A to signal D, and causes the operation of the switch machine 2SM to a corresponding position. Thus, the route is completely selected from signal A to signal D via crossover 2, and, after the track switches have completed their operation to their selected positions, the entering signal A is cleared after the signal control relay AG for that signal has been picked up.

If, however, for some particular reason, such, for example, as on account of a route being established from signal B diverging over track switch 3 reverse, the route from signal A to signal D is not available via crossover 2, but the route from signal A to signal D is available via crossover 4, the available route will be selected. To consider how the route is selected from signal A to signal D via crossover 4, under such conditions, assume that an operator designates the entering point for such route and causes the picking up of the entrance relay ANR and the picking up of the reverse switch control relay 4BR by the energization of circuits which have been described. The picking up of relay ANR does not, however, cause the picking up of relay 4BN, because the circuit which has been described by which relay 4BN is energized when the route is available via crossover 2 is opened at back contact 36 of relay 2BN.

Responsive to the designation of the exit point at signal D, under the assumed conditions, relay DXR is picked up by the energization of a circuit closed from (+), through a circuit including front contact 31 of relay ANR, back contact 32 of

relay AXR, back contact 50 of relay 2AR, wire 115, back contact 116 of relay 4AN, back contact 117 of relay 4BN, front contact 134 of relay 4BR, back contact 120 of relay 4BN, winding of relay DXR, back contact 121 of relay DNR, and contact 122 of button DXB closed in a depressed position, to (-). Upon the picking up of relay DXR a stick circuit is closed at front contact 123 for shunting contacts 121 and 122 out of the circuit just described. Responsive to the picking up of relay DXR relay 4AR is picked up by the energization of a circuit closed from (+), through a circuit including front contact 128 of relay DXR, back contact 129 of relay 4BN, back contact 135 of relay 4AN, and upper winding of relay 4AR, to (-). When relay 4AR is picked up, responsive to the designation of the exit point, the track switches of the cross over 4 are operated to their reverse positions, because relay 4BR is picked up at that time, having been responsive to the designation of the entrance point. After the track switches for crossover 4 have completed their operation to their reverse positions, the entering signal A is cleared because, under the assumed conditions, the track switches of crossover 2 have already been operated to their normal locked positions.

It is believed to be obvious from the above description that if there were more crossovers to the right of crossover 4 in the track layout illustrated in Figs. 1A and 1B, the available route would be selected irrespective of the number of crossovers, via the crossover diverging nearest the designated entrance point.

If it is desirable that the route from signal B to signal E (see Figs. 1A and 4 placed end to end) be kept available whenever possible, rather than providing that the preferred route from signal A to signal D is via crossover 2, it can be provided that the preferred route from signal A to signal D will be via crossover 4 instead of crossover 2. Thus, to illustrate such condition, in Figs. 1A and 4 the preferred route from signal A to signal D is via crossover 4, such preference being provided by the control of the normal and reverse switch control relays for crossover 4. The control of those relays is selected in such a manner that the reverse switch control relay 4BR is given preference over the normal switch control relay 4BN, which is the inverse of the condition which is shown in Fig. 1B for similar relays.

To consider more specifically how such preference is provided, assume, under normal conditions, that an operator desires to set up a route from signal A to signal D. The designation of signal A as an entrance point causes the picking up of relay ANR, and, responsive to the picking up of relay ANR, relay 2BR is picked up by the energization of a circuit which has been described. The picking up of relay ANR also causes the picking up of relay 4BR by the energization of a circuit closed from (+), through a circuit including front contact 31 of relay ANR, back contact 32 of relay AXR, back contact 33 of relay 2AN, back contact 34 of relay 2BN, front contact 35 of relay 2BR, back contact 36 of relay 2BN, back contact 44 of relay 3R, wire 118, back contact 136 of relay 4BR, and center winding of relay 4BN, to (-). The picking up of relay 4BR, however, opens the cir-

cuit just described for relay 4BN at back contact 136 to provide that relay 4BN will remain in a dropped away position, or will be immediately dropped away if it has had time to pick up.

Thus, with relay 4BR picked up, the designation of the exit point at signal D causes the picking up of relay DXR by the energization of a circuit closed from (+), through a circuit including front contact 31 of relay ANR (see Fig. 1A), back contact 32 of relay AXR, back contact 50 of relay 2AR, wire 115, back contact 116 of relay 4AN, front contact 134 of relay 4BR, back contact 120 of relay 4BN, winding of relay DXR, back contact 121 of relay DNR, and contact 122 of button DXB closed in a depressed position, to (-). When relay DXR is picked up, a stick circuit is closed at front contact 123 to shunt contacts 121 and 122 out of the circuit just described. The picking up of relay DXR causes the picking up of relay 4AR by the energization of a circuit which has been described.

After relay 4AR is picked up, relay 2AN (see Fig. 1A) is picked up by the energization of a circuit closed from (+), through a circuit including front contact 128 of relay DXR (see Fig. 4), back contact 129 of relay 4BN, back contact 135 of relay 4AN, front contact 140 of relay 4AR, back contact 141 of relay 4AN, wire 142, back contact 143 of relay 2BR, and center winding of relay 2AN, to (-). Upon the picking up of relay 2AN, relay 2BN is picked up by the energization of a circuit closed from (+), through a circuit including front contact 31 of relay ANR, back contact 32 of relay AXR, front contact 33 of relay 2AN, and upper winding of relay 2BN, to (-). After the track switches are positioned in accordance with their positions selected by the relays 4AR, 4BR, 2AN and 2BN, the signal control relay AG is picked up to clear the entering signal A for that route.

Upon comparing the two methods of control shown for the normal and reverse relays used in the control of the track switches for crossover 4 (comparing Figs. 4 and 1B) it is apparent that the preference is determined by the interlock between the normal and reverse relays.

In Fig. 1B the circuit for the center winding of the normal switch control relay 4BN is so interlocked with the reverse switch control relays for that crossover, that the picking up of reverse relays 4AR and 4BR is necessary in order that the interlock become effective for preventing the picking up of relay 4BN, or in order that relay 4BN will be dropped away by the interlock. The control of the relay 4BR, however, in Fig. 1B, includes in the circuit for its upper winding back contacts of the relays 4AN and 4BN connected in series, thus providing that the picking up of either of relays 4AN or 4BN prevents the picking up of relay 4BR, or causes that relay to be dropped away if it has already had time to be picked up.

With reference to the circuits for relays 4AN, 4BN, 4AR and 4BR as shown in Fig. 4, it will be found that the interlock is provided inversely to the means by which it is provided in Fig. 1B. That is, in Fig. 1B, the interlock is effective to prevent the picking up of relay 4BR only when relays 4AN and 4BN are both picked up to open back contacts 116 and 117 of relay 4AN and 4BN respectively connected in multiple in the circuit for relay 4BR. The picking up of relay 4BR, however, opens the circuit for the center winding of relay 4BN at back contact 136 to prevent the picking up or cause the dropping away of that

relay, as the case may be, irrespective of the position of the other reverse switch control relay 4AR for that crossover.

Thus, by varying the degree of the interlock 5 for each relay, that is, making the interlock for that relay dependent upon one or both of the switch control relays for the opposite position of the track switch, preference can be predetermined as desired for either the normal or the reverse position of a particular track switch.

Indications.—Various means for indicating the condition of occupancy of the various track sections, the condition of the track switches and the routes, and the indications displayed by the signals, can be used with the self-selecting network provided by the present invention. As an example of one means by which the indications can be provided, the indication system shown in Figs. 5A and 5B provides the indications of routes established by a continuous line of light to correspond with each route established. If a train proceeds through a route which has been set up, the portion of the track diagram corresponding to the track section in the route in advance of the train is maintained illuminated by a line of light, and the portion of the track diagram corresponding to the track sections unoccupied in the rear of the train is dark.

The strips of light are provided by use of 30 translucent material for the construction of the track portions of the miniature track diagram, in combination with indicator lamps mounted behind the panel at points corresponding to the track portions or devices for which those indicator lamps are provided. The translucent material for the track diagram, together with any other diffusive means provided, causes uniform illumination throughout the various portions associated with the various lamps. The limits of 35 the portions are clearly defined by suitable baffles 216 (see Fig. 5A) to prevent the light from each of the lamps from extending beyond the portions for which that lamp is provided.

The indicator lamps are illuminated, when setting up a route, for the various portions as soon 40 as those portions are selected as being included in the route. Thus, in view of the fact that the selection of a route builds back from the exit point designated to the entrance point designated, the strips of light follow a corresponding mode of illumination. The portion adjacent the exit point is illuminated first, and the other portions become illuminated as the route is selected. If a track switch included in a route being selected is out of correspondence with the position 45 of that track switch required for that route, the indicator lamp for the position selected is flashed until correspondence is established with the selected controls. After correspondence is established the indicator lamp for that position of the track switch is maintained steadily illuminated.

A lamp of a distinctive color from the switch and route indicator lamps is provided for each strip lighted portion for the purpose of track occupancy indication. Each of such track occupancy indicators is illuminated only when the corresponding track section is occupied by a train. For this embodiment of the present invention it is assumed that the route and switch indicator lamps are white, and that the track occupancy indicator lamps are red. It is to be understood however, that other colors can as well be used, in accordance with the requirements of practice.

75 The signal indications are provided by indica-

tor lamps in the entrance buttons NB. The flashing of a signal indicator lamp is effected upon designation of that entrance point by an operator, and it continues to flash until the signal is cleared for that entrance point, after which it becomes steadily illuminated.

To consider as a specific example of how the indications are provided, assume an operator to designate an entrance point at signal A in setting up a route, as has been described, from signal A to signal E when the normal conditions of the system exist. The picking up of relay ANR responsive to the depression of button ANB causes the flashing of lamp AGE (see Fig. 5A) by the energization of a circuit closed from (+), through a circuit including back contact 170 of the coder CD (see Fig. 5B), wire 171, back contact 172 of relay AG, front contact 173 of relay ANR, and lamp AGE, to (-). Upon designation of the exit point for that route at signal E, the picking up of relay EXR causes the energization of the route indicator lamp D8WE by a circuit closed from (+), through a circuit including front contact 174 of relay EXR (see Fig. 5B), wire 175, front contact 176 of relay 8L¹, front contact 177 of relay 8TR, and lamp D8WE, to (-). The picking up of relays 3R and 3X (see Figs. 1A and 1B) causes the picking up of the switch control relay 3WZ (see Fig. 5A) for that track switch, and the picking up of relay 3WZ causes the flashing of lamp 3RE, because the track switch has not yet been operated to a reverse position, by the energization of a circuit closed from (+), through a circuit including front contact 174 of relay EXR (see Fig. 5B), wire 175, contact 178 of lever 3SML in a center position, front contact 179 of relay 3WZ, front contact 180 of relay 8L¹, front contact 181 of relay 8TR, lamp 3RE, front contact 183 of relay 3WZ, wire 184, and back contact 185 of coder CD, to (-). When the track switch 3 has completed its operation to a reverse position in correspondence with the controls selected, relay 3WZ is dropped away to open the circuit just described for lamp 3RE at front contact 183, and the dropping away of that relay closes a circuit by which lamp 3RE is energized with steady energy from (+), through a circuit including front contact 174 of relay EXR, wire 175, normally closed contact 178 of lever 3SML, front contact 186 of relay 3RCR, front contact 180 of relay 8L¹, front contact 181 of relay 8TR, lamp 3RE, and back contact 183 of relay 3WZ, to (-).

The picking up of relay 3R, in the selection of the route from signal A to signal E, causes the illumination with a steady light of lamp B8WE by the energization of a circuit closed from (+), through a circuit including front contact 174 of relay EXR, wire 175, front contact 187 of relay 3R, front contact 188 of relay 8L, front contact 189 of relay 8TR, and lamp B8WE, to (-). The lamp 2RE is flashed to indicate that a reverse position has been selected for the track switches of the crossover 2, and that those track switches are out of correspondence with such selected positions, by the energization of a circuit closed from (+), through a circuit including front contact 174 of relay EXR (see Fig. 5B), wire 175, front contact 187 of relay 3R, front contact 190 of relay 2BR, contact 191 of lever 2SML in a center position, front contact 192 of relay 2WZ, front contact 193 of relay 7L, front contact 194 of relay 8L, front contact 195 of relay 7TR, front contact 196 of relay 8TR, lamp 2RE, front contact 198 of relay 2WZ, wire 199, and back con-

tact 200 of coder CD, to (-). After the track switches of crossover 2 have been operated to their reverse positions, the relay 2WZ is dropped away, and the reverse correspondence relay 2RCR is picked up to close a circuit for the steady energization of lamp 2RE by a circuit closed from (+), through a circuit including front contact 174 of relay EXR, wire 175, front contact 187 of relay 3R, front contact 190 of relay 2BR, contact 191 of lever 2SML in a center position, front contact 192 of relay 2RCR, front contact 193 of relay 7L, front contact 194 of relay 8L, front contact 195 of relay 7TR, front contact 196 of relay 8TR, lamp 2RE, and back contact 198 of relay 2WZ, to (-).

After relay 8AR is picked up in the selection of a route from signal A to signal E, the route indicator lamp A1WE is steadily illuminated by the energization of a circuit closed from (+), through a circuit including front contact 174 of relay EXR (see Fig. 5B), wire 175, front contact 187 of relay 3R, front contact 190 of relay 2BR, front contact 202 of relay 2AR, front contact 203 of relay 7L, front contact 204 of relay 7TR, and lamp A1WE, to (-).

Upon the clearing of signal A, the lamp AGE in button ANB ceases to flash because of the opening of back contact 172 of relay AG, and it is maintained steadily energized because of the closing of front contact 172 of relay AG.

Upon the clearing of signal A, the lock relays 7L, 8L, and 8L¹ are dropped away as the route locking becomes effective, and the dropping of those relays establishes circuits for maintaining the indicator lamps lighted for the various stretches of the miniature track diagram illustrated as long as the route locking is effected. Thus, the dropping away of relay 7L closes a circuit for the white indicator lamp A1WE from (+), through a circuit including back contact 203 of relay 7L, front contact 204 of relay 7TR, and lamp A1WE, to (-). A circuit is closed upon the dropping away of relay 8L for the energization of lamp 2RE, from (+), through a circuit including back contact 205 of relay 2NCR, back contact 194 of relay 8L, front contact 195 of relay 7TR, front contact 196 of relay 8TR, lamp 2RE, and back contact 198 of relay 2WZ, to (-). Connected in multiple with back contact 194 of the circuit just described is back contact 193 of relay 7L, to provide that relay 2RE is energized when either of the two lock relays is dropped away. The dropping away of relay 8L also closes a circuit for the indicator lamp B8WE from (+), through a circuit including back contact 188 of relay 8L, front contact 189 of relay 8TR, and lamp B8WE, to (-). When relay 8L¹ is dropped away, the circuit is established for the reverse indicator lamp 3RE, from (+), through a circuit including back contact 206 of relay 3NCR, back contact 180 of relay 8L¹, front contact 181 of relay 8TR, lamp 3RE, and back contact 183 of relay 3WZ, to (-). The dropping away of relay 8L¹ closes a circuit for the energization of lamp D8WE, from (+), through a circuit including back contact 206 of relay 3NCR, back contact 176 of relay 8L¹, front contact 177 of relay 8TR, and lamp D8WE, to (-). Thus, the dropping away of the lock relays establishes circuits for the indicator lamps which maintains the steady illumination of a continuous strip of light on the miniature track diagram from the entrance button ANB, to the exit button EXB.

To consider how the presence of a train is indicated through the various portions of the

route, and how the lamps are extinguished for the track sections in the rear of a train, assume a train to accept signal A when a route has been set up from signal A to signal E. The dropping away of relay ANR when the train enters track section 7T causes the signal indicator lamp AGE to be extinguished by the opening of front contact 173, and the dropping away of relay 7TR also causes the white lamp A7WE to be extinguished by the opening of front contact 204. The red lamp for that portion of the track diagram is illuminated, upon the dropping away of relay 7TR, by the energization of a circuit closed from (+), through a circuit including back contact 203 of relay 7L, back contact 204 of relay 7TR, and lamp A7RE, to (-). The dropping away of relay 7TR also causes the white reverse indication lamp 2RE for the crossover 2 to be extinguished by the opening of front contact 195, and the red lamp associated with the reverse position of the track switches for that crossover to be illuminated by the energization of a circuit closed from (+), through a circuit including back contact 205 of relay 2NCR, back contact 194 of relay 8L, back contact 195 of relay 7TR, lamp 7-8RE, and back contact 198 of relay 2WZ, to (-). Thus, the continuous stretch of light from the entrance button ANB to the lower of the two parallel tracks over crossover 2 is illuminated by the energization of red lamps to indicate the presence of a train in track section 7T of the route which has been established.

As the train proceeds through the route and enters track section 8T, the white route indicator lamp B8WE is deenergized by the opening of the circuit for that lamp at front contact 189 of relay 8TR, and the red indicator lamp for that portion of the track diagram is illuminated by the energization of a circuit closed from (+), through a circuit including back contact 188 of relay 2AN, back contact 189 of relay 8TR, and lamp C8RE, to (-). Upon the dropping away of relay 8TR the reverse indicator lamp 3RE is extinguished by the opening of the circuit for that lamp at front contact 181, and the red indicator lamp E8RE is illuminated by the energization of a circuit closed from (+), through a circuit including back contact 206 of relay 3NCR, back contact 180 of relay 8L¹, back contact 181 of relay 8TR, lamp E8RE, and back contact 183 of relay 3WZ, to (-). The white lamp D8WE is extinguished upon the dropping away of relay 8TR, by the opening of the circuit for that lamp at front contact 177, and the illumination of the red lamp F8RE for that portion of the track diagram is effected by the energization of a circuit closed from (+), through a circuit including back contact 206 of relay 3NCR, back contact 176 of relay 8L¹, back contact 177 of relay 8TR, and lamp F8RE, to (-).

When the train leaves track section 7T, the picking up of the relay 7TR causes the picking up of the lock relay 7L, and the picking up of the lock relay 7L, opens the circuit just described for lamp A7RE to cause that lamp to be extinguished. The lamp A7WE cannot be illuminated because the circuit by which that lamp had initially been energized is open at that time because of the dropped away position of the exit relay EXR to open front contact 174. The red lamp 7-8RE for the crossover 2 is, however, maintained energized because relay 8TR is dropped away to close back contact 196 which is connected in multiple with back contact 195 of relay 7TR. When the train leaves the interlocked

group, the red indicator lamps 7-8RE, C8RE, E8RE and F8RE are extinguished because of the opening of the circuits for those relays by the picking up of relay 8TR at back contacts 196, 189, 181 and 177 respectively.

To consider as another typical example of how the indications are provided by a continuous line of light through the miniature track diagram to correspond with the route established, assume that an operator designates signal B as an entrance point in setting up a route from signal B to signal E when the normal conditions of the system prevail as they have been described. The picking up of relay BNR causes the flashing of the signal indicator lamp BGE by the energization of a circuit similar to that described for the flashing of lamp AGE. The designation of the exit point at signal E to cause the picking up of relay EXR causes the illumination of the white indicator lamps D8WE, 3RE and B8WE by the energization of circuits which have been described. Because of the track switches of the crossover 2 being initially in their normal position, the correspondence relay 2NCR is picked up as soon as the normal position of the track switch for that crossover is selected. The picking up of relay 2NCR causes the steady illumination of the normal indicator lamp 2BNE by the energization of a circuit closed from (+), through a circuit including front contact 174 of relay EXR (see Fig. 5B), wire 175, front contact 187 of relay 3R, back contact 190 of relay 2BR, contact 206 of lever 2SML in a center position, front contact 207 of relay 2NCR, front contact 208 of relay 8L, front contact 209 of relay 2BN, front contact 210 of relay 8TR, lamp 2BNE, and back contact 211 of relay 2WZ, to (-). If, however, the track switches for the crossover 2 are out of correspondence with the normal position selected, the picking up of relay 2WZ causes the flashing of lamp 2BNE by the energization of a circuit closed from (+), through a circuit including front contact 174 of relay EXR (see Fig. 5B), wire 175, front contact 187 of relay 3R, back contact 190 of relay 2BR, contact 206 of relay 2SML in a center position, front contact 212 of relay 2WZ, front contact 208 of relay 8L, front contact 209 of relay 2BN, front contact 210 of relay 8TR, lamp 2BNE, front contact 211 of relay 2WZ, wire 184, and back contact 185 of coder CD, to (-).

The route indicator lamp A8WE is illuminated by the energization of a circuit closed from (+), through a circuit including front contact 174 of relay EXR (see Fig. 5B), wire 175, front contact 187 of relay 3R, back contact 190 of relay 2BR, front contact 213 of relay 8L, front contact 214 of relay 8TR, and lamp A8WE, to (-). After the track switches have been properly positioned for the route designated, the signal control relay BG is picked up to cause the steady energization of the signal indicator lamp BGE, and at that time the route set up is definitely indicated by a continuous stretch of white light extending throughout the entire route selected. The clearing of signal B causes the dropping away of relays 8L and 8L¹ to close circuits for maintaining the lamps for the route energized as long as the portions of the route with which those lamps are associated is maintained established.

Upon the dropping away of relay 8L, a circuit is closed for the energization of the white lamp A8WE from (+), through a circuit including back contact 215 of relay 2RCR, back contact 213 of relay 8L, front contact 214 of relay 8TR, and lamp A8WE, to (-). A circuit is closed at

the same time for the white lamp 2BNE, from (+), through a circuit including back contact 215 of relay 2RCR, back contact 208 of relay 8L, front contact 209 of relay 2BN, front contact 210 of relay 8TR, lamp 2BNE, and back contact 211 of relay 2WZ, to (-). Circuits are closed for the energization of lamps B8WE, 3RE and D8WE, upon the dropping away of relays 8L and 8L¹ in a manner which has been described.

Upon passage of a train past signal B, the dropping away of relay BNR causes the extinguishing of signal indicator lamp BGE, and the dropping away of relay 8TR also causes the extinguishing of the white lamps A8WE, 2BNE, B8WE, 3RE and D8WE, by the opening of front contacts 214, 210, 189, 181 and 177, respectively.

The dropping away of relay 8TR causes the energization of the red indicator lamp A8RE by the closing of a circuit from (+), through a circuit including back contact 215 of relay 2RCR, back contact 213 of relay 8L, back contact 214 of relay 8TR, and lamp A8RE, to (-). The dropping away of relay 8TR causes the energization of the red indicator lamp B8RE by the closing of a circuit from (+), through a circuit including back contact 215 of relay 2RCR, back contact 208 of relay 8L, front contact 209 of relay 2BN, back contact 210 of relay 8TR, lamp B8RE, and back contact 211 of relay 2WZ, to (-). The red lamps C8RE, E8RE and F8RE are energized by the closing of circuits which have been described. When the train leaves the route, the picking up of relay 8T allows the picking up of the lock relays 8L and 8L¹, and the picking up of those relays causes the red lamps associated with that route to be extinguished, and that portion of the miniature track diagram to become dark to indicate that the route has been released.

It is believed, upon considering the above described circuits as typical, that it will be readily apparent how the system provided by the present invention for providing the indications can be applied to any particular track layout encountered in practice. Upon considering the circuits just described for the energization of the indicator lamps when the lock relays L are dropped away, it will be noted that, when a route includes one of the track switches of a crossover in a normal position, the normal switch control indicator lamp BNE for that particular end of the crossover only is illuminated, even though, after the route has been completely selected, the normal switch control relay for the opposite end of the crossover is also picked up. Such selection of the indicator lamp which is included in the route actually selected, is effective because of the general organization of the circuits by which the initial illumination of the indicator lamps is effected by the energization of circuits which receive energy dependent upon the exit relay XR for the exit point designated. Thus, in such a circuit network selection system, the lamps are energized to correspond in the miniature track diagram with the route actually selected. After the entering signal for a route has been cleared, and the lock relays L for the track sections in that route have been dropped away, the indicator lamps are dependent upon such lock relays for energization, thus providing, in the control of the normal switch indicator lamps ANE and BNE for each crossover, that the normal switch control indicator lamp can be illuminated only for the end of the crossover which is included in

the route which is set up. Such selections provide that each of the indicator lamps ANE and BNE is illuminated whenever a route is established through the track switch for its respective end of the crossover, each lamp being energized upon the selection of a route past that end of the crossover in a normal position.

It will also be noted from the above description that, after the lock relays have been dropped away, when a route has been completely established, the red indicator lamps RE for indicating track occupancy are illuminated upon passage of a train only for the portions of the miniature track diagram which correspond with the route established, irrespective of how far the track section extends into portions of the track layout not included in the route which is set up. Such selection of the indication lights is provided, for example, as in the circuits for lamps A8WE and A8RE which are selected to be energized upon the dropping away of the lock relay 8L, only when the reverse correspondence relay 2RCR is dropped away to close back contact 215 in correspondence with a route selected with the track switches of crossover 2 in normal positions.

Inasmuch as it is desirable that the switch indicator lamps be illuminated responsive to the designation of switch controls by the actuation of the auxiliary switch control levers SML as well as responsive to the designation of the route ends, it is provided that those switch indicator lamps are illuminated to provide similar switch indications to those which have been described responsive to the picking up of the normal and reverse 35 switch control relays respectively in accordance with the position to which the particular auxiliary lever SML for that particular track switch is operated. Thus, for example, if an operator actuates the lever 2SML (see Fig. 5A) to a position 40 to cause the contacts associated with that lever to be operated to a right hand position, after the relays 2AN and 2BN have been picked up, a circuit is closed for the steady energization of lamp 2ANE, if the track switches of crossover 2 are already in their normal positions, from (+), through a circuit including contact 218 of lever 2SML in a right hand position, front contact 219 of relay 2NCR, front contact 220 of relay 7L, front contact 221 of relay 2AN, front contact 50 222 of relay 7TR, lamp 2ANE, and back contact 198 of relay 2WZ, to (-). At the same time the steady illumination of lamp 2BNE is effected by the energization of a circuit closed from (+), through a circuit including contact 223 of lever 55 2SML in a right hand position, front contact 207 of relay 2NCR, front contact 208 of relay 8L, front contact 209 of relay 2BN, front contact 210 of relay 8TR, lamp 2BNE and back contact 211 of relay 2WZ, to (-). If the track switches of crossover 2 are not in their normal position at a time when relays 2AN and 2BN are picked up, the indicator lamps 2ANE and 2BNE will be flashed until correspondence with the normal position selected is effected. Under such conditions the flashing of lamp 2ANE is effected by the energization of a circuit closed from (+), through a circuit including contact 218 of lever 60 2SML in a right hand position, front contact 224 of relay 2WZ, front contact 220 of relay 7L, front contact 221 of relay 2AN, front contact 222 of relay 7TR, lamp 2ANE, front contact 198 of relay 2WZ, wire 199, and contact 200 of coder CD, to (-). If the track switches are out of correspondence the lamp 2BNE is also flashed by the 75

energization of a circuit closed from (+), through a circuit including contact 223 of lever 2SML in a right hand position, front contact 212 of relay 2WZ, front contact 208 of relay 8L, front contact 209 of relay 2BN, front contact 210 of relay 8TR, lamp 2BNE, front contact 211 of relay 2WZ, wire 184, and contact 185 of coder CD, to (-).

If the lever 2SML is operated to a reverse operating position to cause the contacts associated with that lever to be operated to a left hand position, the reverse indicator lamp 2RE is steadily illuminated, if the track switches are in reverse locked positions, after the reverse correspondence relay 2RCR is picked up, by the energization of a circuit closed from (+), through a circuit including contact 218 of lever 2SML in a left hand position, front contact 201 of relay 2RCR, front contact 193 of relay 7L, front contact 194 of relay 2AN, front contact 195 of relay 7TR, front contact 196 of relay 8TR, lamp 2RE, and back contact 198 of relay 2WZ, to (-). If the track switches of crossover 2 are not in their reverse positions at a time when the auxiliary lever 2SML is operated to a reverse operating position, the flashing of lamp 2RE is effected after the switch control relay 2WZ is picked up by the energization of a circuit closed from (+), through a circuit including contact 218 of lever 2SML in a left hand position, front contact 192 of relay 2WZ, front contact 193 of relay 7L, front contact 194 of relay 8L, front contact 195 of relay 7TR, front contact 196 of relay 8TR, lamp 2RE, front contact 198 of relay 2WZ, wire 199, and contact 200 of coder CD, to (-).

Inasmuch as the moving of a lever SML from its center position to an operating position prevents the feeding of energy back into the circuit network for the control of the indicator lamps for the various track portions along the route, it is believed to be readily apparent that only the lamps associated with indicating the position of the track switch for the particular auxiliary switch control lever operated are illuminated responsive to the operation of the lever to an operating position. That is, for example, the operation of lever 2SML from its center position opens the normally closed center contact 206 of that lever and prevents energy from feeding back into the circuit network when the lamp 2BNE is energized in accordance with the closing of contact 223 of lever 2SML.

Although only one embodiment of the present invention is shown and described in this disclosure, it is to be understood that the system is applicable to any track layout encountered in practice, and it is also to be understood that various novel features of the present invention can be used with other systems. The entire system as provided by the present invention can be divided into a number of subcombinations, each subcombination providing novel features which are applicable for use with other entrance-exit systems and with other track layouts. For example, the route selecting system, the system for execution of switch controls, the switch and signal control circuits, and the control of indications can each be considered a subcombination providing novel features applicable to other systems, and varying requirements of practice.

To consider the route selecting system as a subcombination, with reference to Figs. 1A and 1B, the circuits for the upper windings of relays AN and BN are not essential as those windings are concerned only with the execution of the switch controls. Thus the self-selecting system pro-

vided by the present invention can be used without any execution circuits, or with other types of execution circuits developed in accordance with the requirements of practice. For similar reasons 5 the execution system used in accordance with the present invention would be applicable to a modification of the self-selecting system.

The circuits shown in Fig. 2 for the control of the switch machine 2SM can as well be applied 10 to any system in which normal and reverse switch control relays in a self-selecting network select the position for each track switch, such, for example, as the system shown in the application of Wight and Langdon, Ser. No. 245,384, filed December 13, 1938.

Having thus described as one specific embodiment of the present invention how the system is applied to a particular condition encountered in practice, it is desired to be understood that this 20 form is selected to facilitate in the disclosure of the invention rather than to limit the number of forms that the invention may assume, and, it is to be further understood that various modifications, adaptations and alterations may be applied to the specific form shown to meet the requirements of practice, without in any manner departing from the spirit or scope of the present invention except as limited by the appending claims.

What I claim is:

1. In a switch control system for governing the power operation of track switches and crossovers of a track layout to set up different routes between signal locations at the opposite ends of a track layout by merely designating the entrance and exit ends of such routes, said track layout affording at least two alternative routes between the same signal locations on the opposite ends of said track layout, a normal and a reverse switch control relay for each of said track switches for respectively controlling its normal and reverse operation, one conditioning circuit network having feed points for each signal location governing train movement from right to left and having circuit portions conforming to said track layout, said circuit portions for the normal or reverse position of each switch which would be trailed in the corresponding position by a train moving to the left from such signal locations being connected to the corresponding normal or reverse switch control relay for such switch and being connected to the next circuit portion to the left only when such normal or reverse switch control relay is picked up, each of said circuit portions for the normal and reverse positions of each switch also including back contacts of the switch control relay for the opposite position of that switch, each normal circuit portion for the switch of a crossover which includes a normal relay also including a back contact of the reverse switch control relay for the switch at the opposite end of that crossover in multiple with the back contact of the reverse switch control relay for the same end of that crossover, another conditioning circuit network having feed points for each signal location governing train movement from left to right and having circuit portions conforming to said track layout, said circuit portions for the normal or reverse position of each switch which would be trailed in the corresponding position by a train moving to the right from such signal locations being connected to the corresponding normal or reverse switch control relay for such switch and being connected to the next circuit portion to the right only when such normal or

reverse switch control relay is picked up, each of said circuit portions for the normal and reverse positions of each switch also including back contacts of the switch control relay for the opposite position of that switch, each normal circuit portion for the switch of a crossover which includes a normal relay also including a back contact of the reverse switch control relay for the switch at the opposite end of that crossover in multiple with the back contact of the reverse switch control relay for the same end of that crossover, and circuit means responsive to the manual designation of a particular signal location as the entrance end of a route for applying energy to that conditioning network having a feed point for that entrance signal location and responsive to the subsequent manual designation of a signal location as the exit end of such route for applying energy to that conditioning network having a feed point for such exit signal location, whereby the sequential energization of said conditioning networks in the case of said two alternative routes causes a predetermined one of such routes to be established.

2. In a switch control system of the entrance-exit type provided for setting up different routes through a track layout by the power operation of the track switches at the opposite ends of crossovers in response to only the designation of the entrance and exit ends of a route, a control panel corresponding to said track layout, manually operable contact means upon said control panel for each entrance and exit point for designating the corresponding point as the entrance or exit end of a route, normal and reverse switch control relays for each of said track switches, one conditioning circuit means responsive to the operation of a manually operable contact means designating the corresponding point as the entrance end of a route for energizing the normal or reverse switch control relay for each of the track switches which would be trailed in the corresponding position by a train passing over any available route emanating from such entrance point, another conditioning circuit means responsive to the actuation of a manually operable contact means designating the corresponding point as the exit end of a particular one of said available routes for energizing the normal or reverse switch control relays for each of the track switches which would be trailed in the corresponding position by a train passing from such exit point toward said entrance point over said particular route as preselected by the energization of said one conditioning circuit means, circuit means associated with each crossover and responsive to the energization of the normal switch control relay for that end of the crossover included in a particular route by the supply of energy over one of said conditioning circuits from one end of such route for causing the normal switch control relay for the opposite end of such crossover to be energized by the supply of energy over the other of said conditioning circuits from the opposite end of such route, whereby there are two normal or two reverse switch control relays energized for each crossover included in any given route, and switch control circuit means for each crossover effective to cause the power operation of the track switches of that crossover when and only when two switch control relays are energized for such crossover.

3. In a switch and signal control system of the character described; a track layout having a plurality of tracks connected by a plurality of cross-

overs to form a plurality of conflicting routes extending between entrance and exit points at the ends of the various routes, manually operable contact means for designation of each of the various entrance and exit points; two normal and two reverse switch control relays only for each crossover; circuit means for energizing either one normal or one reverse switch control relay, dependent upon the position of the track switches required, 5 for the trailed end of each crossover having either or both of its track switches included in any available route emanating from each designated entrance point; circuit means for energizing the other normal or reverse switch control 10 relay, dependent upon the position of the track switch required, for said trailed end of each crossover having either or both of its track switches included in a route extending from said designated entrance point to a designated exit point, if that route is available, said circuit means being dependent jointly upon designation of an entrance and an exit point for energizing the normal switch control relay for the opposite end of each crossover when the route having both of its 15 ends designated includes a track switch of that crossover in a normal position and a first normal switch control relay for that crossover has already been energized by designation of the entrance point and circuit means for causing the 20 power operation of the track switches in accordance with the position of the associated normal and reverse switch control relays, only when two normal or two reverse switch control relays are energized for that crossover, whereby the operation 25 of track switches is effected only for the crossovers which have one or both of their track switches included in a route extending between the entrance and exit points designated.

4. In a switch and signal control system of the 30 entrance-exit type; a track layout having a plurality of tracks connected by crossovers to form a plurality of conflicting routes extending between entrance and exit points at the various route ends; manually operable contact means effective 35 when actuated for designation of each of said entrance and exit points; two normal switch control relays only for each crossover, one of said relays for the track switch at each end of the crossover; circuit means for energizing one of said 40 normal switch control relays if that end of the corresponding crossover would be trailed normal upon passage of a train over any available route from a designated entrance point; circuit means for energizing one of said normal switch control 45 relays when that end of the corresponding crossover would be trailed normal if a train were to pass from a designated exit point to a designated entrance point; circuit means responsive to the picking up of one normal switch control relay for each crossover for energizing the normal switch 50 control relay for the opposite end of that crossover only if a route having both of its ends designated includes a track switch of that crossover in a normal position; and circuit means for causing the 55 operation of the track switches at the ends of each crossover only when both of the normal switch control relays for the corresponding crossover are energized; whereby the operation of the track switches for any crossover to a normal position can be effected only when one end of that 60 crossover is included in a route extending between entrance and exit points designated.

5. In a switch and signal control system of the 65 entrance-exit type; a track layout including a plurality of track switches, at least one of which

is a single track switch, to provide a plurality of conflicting routes extending between entrance and exit points; manually operable contact means effective when actuated to designate any particular entrance and any particular exit point for a route to be set up; a normal and a reverse switch control relay for each single track switch; circuit means for energizing a normal or a reverse switch control relay, dependent upon the position of the track switch required, for each single track switch that can be trailed by a train in an available route emanating from a designated entrance point and for each single track switch that would be trailed if a train were to pass over an available route from a designated exit point to the entrance point designated; an execution switch control relay for each single track switch; circuit means for energizing said execution switch control relay if a normal or a reverse switch control relay for that track switch is picked up, only if a route having both of its ends designated includes that track switch; and switch operating means effective for positioning each single track switch in accordance with its normal or reverse switch control relay energized, only if said execution relay for that track switch is picked up; whereby the positioning of a single track switch is effected in accordance with a normal or a reverse switch control relay energized only if that track switch is included in a route extending between entrance and exit points designated.

6. In a switch and signal control system, a switch machine for power operating a track switch to normal and reverse locked positions, a signal for governing traffic over said track switch, a normally deenergized switch control relay energizable to normal and reverse controlling positions for applying energy to said switch machine to cause its normal or reverse operation respectively and for removing all energy from said switch machine when deenergized, a switch position relay energized to a normal or a reverse indicating position when said track switch is in a corresponding normal or a reverse locked position but is deenergized whenever said track switch is unlocked, manually controlled route establishing means for selecting the position of said track switch and for governing the clear and stop indications of said signal rendered effective by the designation of the entrance and exit ends of any given route, circuit means conditioned by said route establishing means to energize said switch control relay to a normal controlling position but rendered effective only when said switch position relay indicates said switch to be in a reverse position or unlocked, circuit means conditioned by said route establishing means to energize said switch control relay to a reverse controlling position but rendered effective only when said switch position relay indicates said switch to be in a normal position or unlocked, and circuit means for clearing said signal governed by said route establishing means and rendered effective only when said switch position relay indicates said switch to be in a normal or reverse locked position corresponding to the normal or reverse position selected by said route establishing means and only if said switch control relay is then deenergized.

7. In a switch and signal control system of the type described for setting up different routes between signal locations of a track layout including at least one power operated track switch, a switch machine for power operating said track switch to normal and reverse locked positions, a

normally deenergized switch control relay energizable to normal and reverse controlling positions for applying energy to said switch machine to cause its normal or reverse operation respectively and for removing all energy from said switch machine when deenergized, a switch position relay energized to a normal or a reverse indicating position when said track switch is in a normal or reverse locked position but is deenergized whenever said track switch is unlocked, normally inactive route establishing means rendered active in response to the designation of the entrance and exit ends of a route including said track switch for selecting the position of that track switch as required to set up such route and for closing an entrance contact at the entrance to the route, circuit means rendered effective by said route establishing means in an active condition to energize said switch control relay to a normal controlling position only when said switch position relay indicates said switch to be in a reverse position or unlocked, circuit means rendered effective by said route establishing means to energize said switch control relay to a reverse controlling position only when said switch position relay indicates said switch to be in a normal position or unlocked, whereby said switch control relay is operated to a normal or reverse energized controlling position only until said track switch has operated to the position required by said route establishing means, a normal correspondence relay for said track switch energized only when said track switch is in a normal position in correspondence with the normal position selected by said route establishing means in an active condition and then only if said switch control relay is deenergized, a reverse correspondence relay energized only when said track switch is in a reverse position corresponding to the reverse position selected by said route establishing means in an active condition and then only if said switch control relay is deenergized, and circuit means for clearing said signal at the entrance end of a route including said entrance contact for that end of the route and contacts closed by said normal or reverse correspondence relays as required for the particular route then selected by said route establishing means.

8. In a switch and signal control system, a switch machine for operating a track switch to normal and reverse positions, a switch control relay energizable to normal and reverse controlling positions for applying energy to the normal or the reverse control wires respectively of said switch machine and for removing all energy from said switch machine when deenergized, a switch position indicating relay for indicating the normal and reverse positions of said track switch and the unlocked or operating condition of said track switch, manually controlled normal and reverse contacts, circuit means conditioned upon the closure of a manually controlled normal contact for energizing said switch control relay to a normal control position but rendered effective only when said switch indicating relay indicates said track switch to be in a reverse position or unlocked, circuit means conditioned upon the closure of a manually controlled reverse contact for energizing said switch control relay to a reverse control position but rendered effective only when said switch indicating relay indicates said track switch to be in a normal position or unlocked, and signal clearing circuits controlled in accordance with the position of said track switch and de-

pendent upon the deenergized condition of said switch control relay.

9. In a switch and signal control system for railroad track layouts having a plurality of power-operated track switches movable to different positions to set up various routes for train movement between signal locations, certain of said routes being conflicting and others non-conflicting comprising in combination with a control panel having thereon a miniature track diagram of the track layout, manually operable control buttons located on said track diagram adjacent the signal locations represented thereon, route establishing means responsive to the joint operation of a control button at the entrance to a route and a control button at the exit end of that route to effect the control of the track switches of said track layout to positions required to set up such route, indicating means associated with said track diagram for illuminating linear portions of the track for the different positions of the track switches represented thereon and also for illuminating linear portions of the track represented thereon extending between the several track switches, circuit means controlled by said route establishing means to cause said indicating means to intermittently illuminate the linear portions for the new positions of those track switches included in any route being set up until such track switches have assumed those positions in correspondence with such positions as required by said route establishing means to complete the route designated, and other circuit means controlled by said route establishing means upon the designation of any given route for causing the steady illumination of the linear portions interconnecting the track switches included in such given route.

10. In a switch and signal control system of the character described, a control panel having thereon a miniature track diagram of the track layout under the control of the operator, the lines of said track diagram being formed by closely spaced strips of glass associated with the different positions of each switch and intervening portions, two lamps of different colors for illuminating each of said strips, route establishing means including manually operable buttons associated with said track diagram for governing the power operation of switches and the clearing of signals for any route in response to the actuation of buttons to designate the entrance and exit ends of that route, circuit means responsive to the operation of said route establishing means to initiate switch operation for a route for lighting the lamps of one color for all of the strips of the track diagram corresponding with the portions of track and positions of switches included in said route and thereby outline said route by a substantially continuous line of light throughout its length, said circuit means acting to light intermittently the lamps for each of said strips relating to the normal or reverse position of each switch to be operated from its existing position only until said switch has operated to the position required for the route, and track circuit controlled means for extinguishing said lamps of said first color and for lighting the lamps of the other color for those strips relating to each track section while it is occupied by a train.

11. In a switch and signal control system of the entrance-exit type, a control panel having thereon a miniature track diagram of the track layout under the control of the operator, route

establishing means including manually operable buttons associated with said track diagram for governing the power operation of switches and clearing of a signal for any route upon actuation of buttons to designate the entrance and exit ends of said route, indicating means including a lamp for illuminating a substantially linear portion of said track diagram for each position of each switch and each portion intervening between switches, and circuit means responsive to the operation of said route establishing means to initiate operation of switches for a route to light a lamp for all of said portions of said track diagram included in said route and thereby outline said route to be established by a substantially continuous line of light throughout its length, said means acting to intermittently light the lamp for the position of each switch required for that route while said switch is being operated to that position and to steadily light said lamp after that switch has been operated to such required position for the route, and thereby visually indicate by the flashing or steady illumination of the indicating means associated with the positions of the switches what position of each switch is included in an initiated route and when the switch has operated to that required position.

12. In a switch and signal control system of the entrance-exit type, a railroad track layout having power operated track switches interconnected by stretches of track for setting up different routes between signal locations, a control panel including transparent linear portions arranged to represent the different positions of the track switches of the track layout and also the adjoining stretches of track, a lamp for each of said linear portions, control buttons for the entrance and exit ends of the routes, route establishing means rendered active in response to the control buttons for the entrance and exit ends of any given route for setting up that route and clearing a signal at the entrance end thereof and at the same time rendering said route establishing means ineffective to establish any conflicting route, a normally inactive auxiliary lever associated with each switch and manually operable to normal and reverse controlling positions, means controlled by each of said auxiliary levers in normal and reverse controlling positions for effecting the corresponding operation of its respective track switch and at the same time rendering said route establishing means ineffective to establish any route conflicting with such position of that track switch, circuit means controlled by said route establishing means when it is rendered active with respect to any switch either by said control buttons designating a route or by the auxiliary lever for that switch for intermittently lighting the lamp for the controlled position of such switch while it is in operation but steadily lighting said lamp when the switch has completed its operation, and circuit means controlled by said route establishing means for steadily lighting said lamps for the adjoining stretches of track when such stretches are included in a route designated by said control buttons.

13. In a switch and signal control system of the entrance-exit type, a track layout including power-operated track switches for setting up different routes between signal locations, a control panel having thereon a miniature track diagram of the track layout, control buttons on the diagram associated with the signal locations, route

establishing means rendered active in response to the operation of the control buttons for designating the entrance and exit ends of any given route for governing the power operation of the switches in such route and clearing the signal for the entrance end of such route, indicating means including a lamp for illuminating a linear portion of said track diagram for each position of each switch and for each adjacent stretch of track, circuit means effective when said route establishing means is rendered active to set up any given route to light a lamp for each portion of said track diagram representing the position of the switches and the stretches of track included in that route, said circuit means acting to intermittently light the lamps for the position of each switch included in said given route if such switch requires operation to that position and continuing to so act only until such switch has completed its operation, a normally inactive auxiliary lever associated with each switch for individually controlling the normal and reverse operation of that switch, and means controlled by each of said auxiliary levers in normal and reverse controlling positions for intermittently lighting the lamp for the corresponding position of said track switch until its operation has been completed.

14. In a switch and signal control system of the entrance-exit type, stretches of track interconnected by power operated track switches to set up different routes between entrance and exit signal locations, said stretches of track being divided into track sections having normally energized track circuits, a control panel including transparent linear portions arranged to represent the different positions of the track switches of the track layout and also the adjoining stretches of track, two lamps of different colors for illuminating each of said linear portions, control buttons for the entrance and exit ends of the routes, a signal indicating lamp associated with the buttons for the entrance ends of the routes, route establishing means responsive to the actuation of the control buttons for the entrance and exit ends of any route for initiating the power operation of the track switches to set up that route and clear the signal at the entrance thereto, circuit means controlled by said route establishing means to light the lamps of one color for all of the portions of the track diagram corresponding to the positions of the switches and stretches of track included in any given route designated by the operation of control buttons for the entrance and exit ends of that route, said circuit means acting to intermittently light the lamps for each of the portions of such route relating to the positions of the switches in the route to which such switches must be operated but acting with respect to any switch only until that switch has been operated to the required position, circuit means controlled by said route establishing means to intermittently light the signal indicator for any given signal as soon as that signal has been designated as an entrance signal location by the actuation of its control button but to steadily illuminate such signal indicator when its associated signal has cleared, track circuit controlled means for extinguishing said lamps of said first color and for lighting the lamps of the other color for those portions of the track diagram relating to each section of track occupied by a train, and track circuit controlled means for extinguishing said signal indicator when a train enters the route.

15. In a switch and signal control system of the entrance-exit type for railroad track layouts, manually operable control buttons associated with a track diagram for designating entrance and exit ends of desired route, an exit relay for the exit end of each route, route establishing means responsive to the operation of control buttons to designate the entrance and exit ends of any desired route for energizing the exit relay of that route and governing the power operation of the track switches of the track layout to establish that route, indicating means including lamps for illuminating substantially linear portions of said track diagram, and a circuit network supplied with an energizing potential in response to the energization of an exit relay for any designated route and including contacts governed by said route establishing means for supplying current to the lamps of said indicating means for indicating in outline the route defined by the operation of the route establishing means.

16. In a switch and signal control system for setting up different routes between signal locations of a railroad track layout by the power operation of the track switches included in the different track sections of such layout, a control panel having a miniature track diagram of said track layout, manually operable control buttons on said control panel for the entrance and exit ends of the different routes, route establishing means responsive to the operation of the manual operable control buttons for the entrance and exit ends of any given route for operating the track switches to establish that route, indication means including lamps for illuminating linear portions of said track diagram to outline the routes designated by the operation of the control buttons by a substantially continuous line of light, a relay associated with each track section and automatically deenergized when that section is included in an established route, said relay when deenergized acting to lock the track switches associated with the corresponding track section, a circuit network including contacts governed by said route establishing means and energized at a feed point corresponding to one end of a route for supplying current to selected lamps of that route defined by the operation of the buttons for the entrance and exit ends thereof, the circuit portions of said network for supplying current to the lamps associated with each track section including a front contact of the corresponding relay and being individually energized when said relay is deenergized.

17. A switch and signal control system of the entrance-exit type for track layouts including parallel tracks connected by one or more crossovers, manually operable buttons for designating the signal locations of said track layout to constitute the entrance and exit ends of desired routes, four switch control relays associated with each crossover and adapted when energized in combination of two each to cause power operation of the crossover to the normal and to the reverse position, two circuit networks for governing the energization of selected relays associated with said crossover, one circuit network having feed points corresponding with the signal locations for one end of the various routes and the other circuit network having feed points corresponding with the signal locations for the opposite ends of said routes, means effective upon actuation of a button to designate a signal location as either the entrance or the exit end

of a desired route to apply an energizing potential to the corresponding feed point of the corresponding network, each network when energized from a given feed point prior to the energization of the other network acting to control the energization of a relay associated with each of the ends of said crossover only disposed in a trailing relation in some available route originating at the signal location corresponding with the feed point energized, each network when energized from a given feed point subsequent to the energization of the other network acting to energize an additional relay for each crossover included in a route terminating at the signal location corresponding with said feed point and thereby cause operation of said crossover to the position required for said route and also deenergizing relays relating to the ends of crossovers in all other routes which were energized by the circuit network first energized.

18. A switch and signal control system of the entrance-exit type for track layouts including parallel tracks connected by one or more crossovers, manually operable buttons designating the entrance and exit ends of desired routes, two relays associated with each crossover and adapted when both are energized to cause power operation of that crossover to the normal position, each of said relays having two windings, initiating circuits energized in response to the actuation of a button to designate an entrance end of one or more routes for energizing one winding of one of said relays relating to the end of each crossover that would be trailed in the normal position for some available route originating at said entrance point, and circuit means responsive to the actuation of a button to designate the exit end of one of said available routes and including contacts closed by the energization of relays energized by said initiating circuits for energizing the other winding of the other relay of each crossover included in said one available route.

19. A switch and signal control system of the entrance-exit type for track layouts including parallel tracks connected by one or more crossovers and affording a plurality of routes between entrance and exit signal locations, manually operable buttons for designating signal locations to constitute the entrance and exit ends of desired routes, four switch control relays associated with each crossover comprising two relays relating to the normal position and two relating to the reverse position, means for operating each crossover to the normal position when both of the relays relating to the normal position are energized and to the reverse position when both of the relays relating to the reverse position are energized, initiating circuits responsive to the operation of a button to designate any given entrance signal location for energizing one of the normal or the reverse relays for each end of a crossover that would be trailed in the corresponding normal or reverse position by train movement over any one of the available routes originating at said entrance signal location, and circuit means responsive to the subsequent actuation of a button to designate the exit end of a particular one of said available routes for energizing the other normal or reverse relay as the case may be for each of the crossovers included in said particular route and thereby cause operation of said crossover to the normal or the reverse position as required to provide said route.

20. In a switch and signal control system of the entrance-exit type for track layouts including parallel tracks connected by one or more crossovers, manually operable buttons for designating the signal locations of said track layout to constitute the entrance and exit ends of routes, four relays associated with each crossover and adapted when energized in different combinations of two relays each to govern operation of said crossovers to the normal and the reverse position, conditioning circuits responsive to the actuation of a button to designate any given entrance signal location for conditioning one of said relays associated with each trailed end of a crossover included in any one of the available routes originating at said entrance signal location and thereby preselect the position of said crossovers to conform with said routes, and circuit means responsive to the actuation of a button to designate the exit end of a particular one of said routes and controlled by the relays conditioned by said initiating circuits for energizing another one of the relays associated with each of those crossovers included in said particular route and deenergizing those relays conditioned by energization of said initiating circuits and relating to all other routes originating at the same entrance signal location.
21. In a switch and signal control system for governing the power operation of the track switches of a track layout comprising two crossovers to set up either of two different routes between two signal locations; a control panel having a track diagram corresponding to said track layout; manually operable contact means on said control panel at points corresponding to the signal locations; normal and reverse switch control relays for each of the track switches of said track layout, whereby there are only two normal switch control relays and two reverse switch control relays for any given crossover; an entrance relay and an exit relay for each of said signal locations; circuit means for energizing the entrance relay for a signal location upon the actuation of the manually operable contact means for that signal location designating it as an entrance point; initiating circuit means responsive to a picked up entrance relay for energizing a normal or a reverse relay for each track switch which would be trailed by a train moving over any available route emanating from the corresponding signal location, said initiating circuit means being so organized as to cause the energization of a normal switch control relay to deenergize a reverse switch control relay whenever both such relays are energized at the same time, circuit means responsive to the actuation of the manually operable contact means for a signal location designating it as an exit point for energizing the exit relay corresponding to such signal location only providing there is an available route between such exit signal location and the signal location designated as an entrance point; completion circuit means responsive to the picked up condition of an exit relay for energizing the normal or reverse switch control relay for each of the track switches which would be trailed by a train moving from the corresponding exit signal location toward the signal location designated as the entrance point over a route preselected by the energization of normal or reverse relays by said initiating circuit network, said completion circuit network also energizing a corresponding normal or reverse switch control relay for each of the track switches.

having a normal or reverse switch control relay energized by said initiating circuit network; and switch control circuit means effective to cause the power operation of the track switches at the opposite end of any crossover to reverse positions only if both of the reverse switch control relays for that crossover are energized, and to cause power operation to normal positions only if both of the normal switch control relays for that crossover are energized.

22. A switch and signal control system of the entrance-exit type described for track layouts including parallel tracks connected by one or more crossovers and having one or more single switches associated therewith, manually operable buttons for designating entrance and exit signal locations and routes over said track layout, three switch control relays associated with each single switch and four switch control relays associated with each crossover and adapted when energized in different combinations of two relays each to govern power operation of the corresponding switch or crossover to the normal and to the reverse position, initiating circuits responsive to the actuation of a button to designate any given entrance signal location for conditioning one of said relays associated with each trailed end of a crossover and each trailed single switch included in any one of the available routes originating at said entrance signal location and thereby preselect the position of said trailed switches and ends of crossovers to conform with said routes, and circuit means responsive to the subsequent actuation of a button to designate the exit end of a particular one of said available routes and governed by the relays conditioned by said initiating circuits for energizing another one of the relays associated with each of the trailed single switches or crossovers included in said particular route and also two relays for each of the remaining switches in that route and in a facing point relation to the designated entrance signal location, said circuit means also deenergizing those relays energized by said initiating circuits and relating to trailed switches in all other routes originating at the same entrance signal location.

23. A switch and signal control system of the entrance-exit type for track layouts including one or more single switches, manually operable buttons for designating the entrance and exit signal locations for routes over said track layout, three switch control relays associated with each single switch and adapted when energized in different combinations of two relays each for governing the power operation of said switch to the normal and reverse position, initiating circuits responsive to the actuation of a button to designate any given entrance signal location for energizing a relay for each switch trailed in either the normal or the reverse position and included in any route originating at said entrance signal location, and circuit means responsive to the subsequent actuation of a button to designate the exit end of a selected one of said routes for energizing another relay associated with each of said trailed switches and a combination of two relays associated with each of the remaining switches in the route which have a facing point relation to the designated entrance signal location and thereby cause operation of the switches to the positions required for said route.

24. In a switch and signal control system for setting up different routes between signal locations of a railroad track layout by the power operation of the track switches of such track layout,

power operating means for each of said track switches, a control panel having a miniature track diagram of said track layout, manually operable contact means on said control panel for each of said signal locations, a normally deenergized polar neutral switch control relay associated with each of said track switches for applying operating energy to the power operating means for its track switch in accordance with whether it is energized to a normal or a reverse controlling position, route establishing means responsive to the actuation of a manually operable contact means for designating an entrance signal location followed by the actuation of a manually operable contact means for designating an exit signal location for causing the energization of the switch control relays for only those switches of that route connecting said signal locations requiring operation from their existing positions to positions required to establish such route, means controlled by the operation of any given switch into correspondence with its switch control relay for deenergizing such relay, and circuit means controlled by said route establishing means for clearing the signal at the entrance end of any established route, said circuits including contacts closed only if the switch control relay for each switch in that route is deenergized.

25. In a switch and signal control system for setting up different routes between signal locations of a railroad track layout by the power operation of the track switches of such track layout, power operating means for each of said track switches, a control panel having a miniature track diagram of said track layout, manually operable contact means on said control panel for each of said signal locations, a normally deenergized polar neutral switch control relay associated with each of said track switches for applying operating energy to the power operating means for its track switch in accordance with whether it is energized to a normal or a reverse controlling position, route establishing means responsive to the actuation of a manually operable contact means for the entrance end of any given route followed by the actuation of a manually operable contact means for the exit end of that route for causing the energization of the switch control relays for the switches of such route to normal or reverse controlling positions as required to establish that given route, means controlled by the operation of said switches into correspondence with their respective switch control relays for deenergizing such relays, and circuits rendered effective for clearing the signal at the entrance end of an established route only when the switch control relay for each switch in that route is deenergized, whereby energy is removed from the power operating means for all the switches of any established route before the signal therefor is cleared.

26. In a switch and signal control system for railroads, a track layout having a plurality of power operated track switches for setting up different routes between entrance and exit signal locations, a normally deenergized polar neutral switch control relay associated with each of said track switches and operable to normal or reverse controlling positions for applying operating energy to the power operating means for its track switch and deenergizing such power operating means when deenergized, manually operable contact means for each of said signal locations, normally inactive route establishing means rendered active in response to the operation of a manually

operable contact means to designate an entrance signal location followed by the actuation of a manually operable contact means to designate an exit signal location for causing the energization of the switch control relays for the switches of the route connecting such entrance and exit signal locations providing the track switches associated with such relays require operation from their existing positions to their opposite positions in order to establish such route, means controlled by the operation of any given switch into correspondence with its switch control relay for de-energizing such relay although said route establishing means is still active with respect to a route including that track switch, means associated with each switch for maintaining its switch control relay energized while such switch is in midstroke although said route establishing means is rendered inactive with respect to such switch, and signal control circuits for clearing the signal at the entrance end of any established route governed by said route establishing means while it is rendered active with respect to that route, said circuits for any given route including contacts closed only if the switch control relay for each switch in that route is deenergized.

27. In a switch and signal control system for setting up different routes between signal locations of a track layout by the power operation of the track switches of such layout, power operated switch machine for each of said track switches, a normal and a reverse circuit for said switch machine, a neutral polar relay having two windings, said relay acting when energized to supply operating energy to a normal or reverse control circuit of said switch machine and when deenergized removing all energy from said switch machine, normal and reverse switch position indicating contacts operated in accordance with the position and locked condition of the track switch, manually controlled circuits for energizing one winding or the other of said neutral polar relay, said circuits including said switch position contacts, normal and reverse correspondence relays having energizing circuits for energizing the normal or reverse relay in accordance with whether the switch position contacts indicate the track switch to be in correspondence with the normal or reverse manual control therefor, said circuits also including back contacts of said neutral polar relay, and signal control circuits including contacts of said correspondence relays.

28. In a switch and signal control system for setting up different routes through a track layout including at least one track switch, a power driven switch machine for operating the track switch, said switch machine having normal and reverse operating circuits, a neutral-polar relay effective when energized to a normal or reverse controlling position for energizing the corresponding normal or reverse operating circuit of said switch machine and when deenergized acting to remove all energy from said switch machine operating circuits, normal and reverse switch position indicating contacts operated in accordance with the normal and reverse positions and locked condition of said track switch, manually governed contacts for closing normal and reverse energizing circuits for said neutral-polar relay, said energizing circuits including said switch position contacts in a manner that said normal circuit is energizable only when said track switch is in a reverse position or unlocked and

that said reverse circuit is energizable only when said switch is in a normal position or unlocked, whereby said neutral-polar relay is energizable when said track switch is to be operated from its 5 existing position and is deenergized when such operation is completed, although said manually governable contacts remain in active positions, normal and reverse correspondence relays, circuits for said normal and reverse correspondence relays including said normal and reverse switch position indicating contacts respectively, said manually governed contacts and back contacts of said neutral-polar relay, signal control circuits selected by contacts of said correspondence relays, and locking means for opening said energizing circuits of said neutral-polar relay when a route is established over said switch or when its associated track section is occupied by a train.

29. In an interlocking control system, a track layout including a plurality of track sections containing track switches which may be arranged to form different traffic routes, route levers for selecting said routes, a locking relay for each section energized only when conditions are proper for the operation of the switch in such section, normal and reverse route relays for each switch, means controlled by each route relay for operating the corresponding switch to its normal or reverse position effective only when the locking 20 relay for that switch is energized, normally de-energized normal and reverse indication relays for each switch, means for energizing each such normal or reverse indication relay when the normal or reverse route relay for the same switch 25 is energized and the switch assumes the corresponding normal or reverse position, route selecting circuits for governing the operation of said route relays as required to establish the route selected by the operation of said route levers, 30 means for releasing the locking relay for each switch of a selected route when such route is established, and means controlled by each such locking relay when released for maintaining energized the normal or reverse indication relay 35 for the associated switch only until such locking relay is again energized.

30. In an interlocking control system, a track layout including track switches operable to normal and reverse positions to form different traffic routes, route levers for selecting said routes, a locking relay for each track switch energized only when conditions are proper for operating the track switch, route relays effective to operate the track switches to normal or reverse as required to establish said traffic routes, means controlled by said route levers to operate said route relays as required to select a particular route, normally deenergized normal and reverse indication relays for each switch, means for energizing the normal or reverse indication relay for each track switch when the switch assumes its normal or reverse position in response to the operation of the corresponding normal or reverse route relay, signals at the ends of said routes for governing traffic movements through the track layout, a signal control relay for each signal effective when energized to clear the corresponding signal, and a circuit network including a circuit for each route through the track layout for controlling said signal control relays, each said circuit including front contacts of the normal or reverse indication relay for each switch of the route, means including contacts controlled by the route levers effective to connect a source of cur- 40 45 50 55 60 65 70 75

rent to one end and the winding of a selected signal control relay to the other end of the circuit for the selected route for energizing such signal control relay when each switch of the route assumes the position required for such route, means controlled by each switch control relay when energized for releasing the locking

5 relay for each switch of the corresponding route, and means controlled by each locking relay for maintaining energized the normal or reverse indication relay for the associated switch only until such locking relay is again energized.

NELSON B. COLEY.

DISCLAIMER

2,265,350.—*Nelson B. Coley*, Rochester, N. Y. SWITCH AND SIGNAL CONTROL SYSTEM FOR RAILROADS. Patent dated December 9, 1941. Disclaimer filed January 17, 1942, by the assignee, *General Railway Signal Company*.

Hereby enters this disclaimer by disclaiming from claims 19 and 20 any system of switch and signal control, except wherein the four relays associated with each crossover and energized in the manner specified, are alone sufficient to operate the crossover to the normal or reversed position as required for establishing any route in either direction over the track layout from any entrance signal location.
